UNITED STATES PATENT OFFICE

2,573,313

RECORD CONTROLLED BILL PRINTING DEVICE

Jonas E. Dayger and Frederick S. Huling, Binghamton, N. Y., assignors to International Business Machines Corporation, New York, N. Y., a corporation of New York

Application April 7, 1950, Serial No. 154,606

13 Claims. (Cl. 235—61.7)

1

This invention relates generally to paper feeding devices and more particularly to machines of the class in which perforated record cards control the preparation of bills.

The main object of the invention is to provide bill feeding and printing mechanism for tabulating machines or other office appliances in which provisions are made for feeding classified bills past a printing station and stopping certain of said bills in print receiving position to receive impressions of data of the same account or classification. The invention is illustrated as applied to an alphabet printing tabulating machine in which the usual perforated record cards are fed through the machine and the perforated data thereon analyzed and used to control the operation of accumulating and printing mechanism. The bill forms are also often in the shape of perforated cards and they are perforated with predetermined account numbers coinciding or related to name and address data already appearing as printed matter on the bill or to be put on by card control. These bill cards are fed through the bill feeding mechanism concurrently with the feeding of the control record cards through the tabulating machine. The classification data of the cards are compared with the account data on the bill form and if they are in agreement recording takes place on the bill under control of perforations in one or more related control cards.

The record cards are arranged in groups and they are fed in succession through the tabulating machine. The bill forms, of which there is usually one for each group of cards, are sent through the bill feeding device and upon agreement of the account number data of the first card of a group with the corresponding data on the bill form, further long feeding of the latter is interrupted and successive printing entries are made thereon under control of one or more of the cards in the group. The bill form is advanced line by line to receive each entry on a different printing line. Usually a total is taken and recorded near the bottom of the bill form before the bill is ejected through the bill feeding device and another bill form brought into the print receiving position.

An object of the invention is the provision of improved comparing devices for determining the agreement or lack of agreement between the account number perforations of a bill form and a concurrently sensed record card. This kind of comparing is known as equal, no-equal comparison and the object is to detect the absence of

2

either bill forms or related groups of records or the presentation of either one in the wrong order. Controls are associated therewith to stop the machine to give the operator the opportunity to insert the proper record or re-arrange the records to the proper order.

Another object of the invention is the provision of an alternate form of comparing control device wherein the relative magnitude between bill account numbers and card account numbers is determined so that one or the other may be advanced to bring about agreement without stopping the machine. This advanced form of comparing control is known as the high, low, equal control whereby bill form or record card feeding may be called into play selectively to pass non-matching records until agreement is reached. For example, if it is sensed that the bill number is lower in sequence than the sensed card number then the bill forms are advanced and passed beyond the printing position successively until an agreeing account number is sensed on a bill form and that one is stopped at the print receiving position to receive data from the corresponding record cards. If, on the other hand, the bill account number is found by the comparing device to be higher than the sensed card account number then the cards are advanced successively through the tabulator while the bill form is stationary until agreement is reached by sensing an account number on a card agreeing with the account number of the bill.

Another object of the invention is the provision of storage devices in cooperation with comparing devices wherein the account number data to be compared are stored successively so that the data of one card can be matched through the storage devices while the data of a succeeding card are being entered therein.

Another object of the invention is the provision of multi-sectional group control devices wherein one section is used to compare group numbers of successively fed cards in one feed unit, and the other section is used to compare account numbers of bills in another feed unit with said cards; said bill and card comparing section involving the use of code relays for inverting and storing a bill reading before said reading is directed into the group control devices to compare with a card passing under the upper brushes of the tabulator.

Another object of the invention is the provision of an economical form of code pickup, inverting and storage relays involving the use of four relays representative of 6, 3, 2, 1 for a com-

binational registration of the digits. Associated with the code relays are resistances and rectifiers for permitting the application of a pre-energizing circuit to cut down on the pickup time and at the same time to eliminate back-circuits which tend to find a path due to the application of pre-energizing current.

Another object of the invention is the provision of error controls for stopping the machine and showing a signal under joint control of card and bill comparing devices when a no-equal condition is found. Runout devices are provided under manipulative control for clearing the machine of both cards and bills so that they can both be rearranged, inserted and withdrawn to conform to two agreeing series of records for perfect billing control.

Another object of the invention is the provision of new and improved high, low, equal, passing controls for comparing records and automatically passing one set or another to get continuous agreement without attention by the operator. Code relays and contacts with labyrinth circuits are involved to secure inversion, storage and comparison of classification data of records such as cards and bills.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a right side elevation of the bill feeding mechanism.

Fig. 2 is a left side elevation of the bill feeding mechanism and is drawn to a slightly larger scale than Fig. 1.

Fig. 3 is a vertical section taken through the center of the bill feeding mechanism and the printing devices.

Figs. 4, 5 and 6 are diagrammatic views showing cycles of number comparisons made with the equal, no-equal form of comparing device.

Figs. 7 to 12, inclusive, are diagrammatic views showing the cycles of comparing operations occurring with the use of the high, low, equal comparing device.

Figs. 13a to 13e, inclusive, show the wiring diagram of the machine involving the use of the equal, no-equal form of control.

Figs. 14a to 14f, inclusive, show the wiring diagram of the machine when provided with the high, low, equal form of comparing device.

Figs. 15, 16, 17 and 18 are timing charts showing the time of operation of the various contacts and relays.

As a matter of convenience in description, the bill attachment has been illustrated in the drawings as applied to an electrical accounting and statistical machine now well known in the art as the "405 International" electric accounting machine. The basic principles of operation of this machine are described in numerous patents to A. W. Mills, J. R. Peirce and others, and the machine shown in general outline in Figs. 1, 2 and 3 may be the same as the ones described in Letters Patents 2,016,682, No. 2,042,324, No. 2,079,418, No. 2,172,067 and No. 2,199,547 which are merely representative of the many patents describing this type of machine. As the mechanism of the machine itself forms but a small part of the bill feeding attachment, only pertinent details of such a machine will be given herein to enable those skilled in the art to understand how the

bill feeding attachment may be applied to a conventional accounting machine.

The numeral 20 (Fig. 1) indicates the main frame of the accounting machine on which are secured right and left side frames 21, 22, respectively, which support the usual Hollerith printer control magnets 23 (Fig. 3) and associated parts of the printing mechanism, the printing magnets being mounted in the side frames 24 of a magnet unit carried by frames 21, 22. These magnets 23 control type-bars 25 in the manner described in the cited patents, the printing line being generally designated in Fig. 3 by the arrow P. The type-bars, as usual, are protected by a housing 26.

A shaft 16 (Fig. 1) projecting through the frame 21 is known as a constantly rotating shaft and, as described in the cited patents, makes one complete revolution for each cycle initiated in any of the ways described in said patents. Attached to this shaft 16 is a bill feed drive gear 17 in mesh with an idler gear 19 loosely pivoted on an assembly plate 18 which also has a shaft 27 for the clutch drive gear 12. Fixed to gear 12 is a clutch disk 13 in axial alignment with the normally idle clutch gear 85. Attached to driven gear 85 is a bell crank 11 which carries the clutch pawl 14. Pawl 14 is spring urged towards engagement with the notch in moving disk 13 but is held out of engagement by the hooked end of armature 15 which only releases the pawl when the bill feed magnet BF is energized. Through the clutch parts 11, 12, 13 and 85 the long feeding movements for operating the bill feed are imparted to the bill feeding attachment. Another train of mechanism is provided for line spacing the item imprints while listing the data derived from the usual perforated record cards.

The ratio of clutch gear 85 to a bill feed drive gear 81 is 2 to 1 and it is possible to engage the bill feed clutch for one half or one complete tabulator cycle by energizing bill feed clutch magnet BF at either or both of the 6° and 186° points in a tabulating cycle.

The line spacing mechanism is operated by a chain of connections extending from the interior of the tabulator up to the platen shaft 113 to turn the platen 112. On operating pin 33 (Fig. 2) fits in a notch 246 in an arm 247 secured to a short shaft 248 journaled in a frame 36. Shaft 248 extends outside and has fixed thereon a slotted arm 249. Adjustably and pivotally mounted in a slot 250 in arm 249 is one end of a link 251 the other end of which is pivoted to an arm 252 loosely mounted on the platen shaft 113.

Arm 252 is secured to one driving element of a double clutch, the driven element 127 of which is fastened to the platen shaft 113.

The means for rocking the line space shaft 248 (Fig. 2) to effect spacing operation is the same as that shown and described in Patent No. 2,181,992.

Fixed to shaft 248 (Fig. 2) is the arm 247 formed with a slot 246 which receives the pin 33 extending from the upper end of a vertical arm on a bell crank 34 (Fig. 1) which is seen to have mechanical connections to control mechanism situated in the lower part of the tabulator. Attached to the horizontal arm of bell crank 34 is an operating link 32, the lower end of which is articulated on another bell crank 31. In Fig. 1, it will be seen that the constantly running worm wheel of the tabulator, has fixed thereto a double cam 28' engaging a lever 29 which is urged

5 by a spring into contact with said cam, and an upwardly extending arm of lever 29 carries a stud which moves in an L-shaped slot of a link 30 connected to the bell crank 31 already mentioned. A nose of link 30 rests upon an armature of a line spacing control magnet LSM. This magnet is energized at a time when the follower roller of lever 29 is on the low portion of cam 28' and the stud is to the right in the L-shaped slot which will permit link 30 to be drawn down into operating relationship with the stud so that, as lever 29 is rocked counterclockwise by the cam, bell crank 31 will be actuated to shift link 32 and cause the operation of the line spacing device. A spring attached to bell crank 31 restores the connected train of parts.

10 Following such paper spacing operation a pin 29' on the worm wheel coacts with a lever 28 to raise link 30 positively out of engagement with the stud on lever 29 and cause it to be latched on the armature of magnet LSM.

15 Summarizing, it will be evident that the tabulator includes an operating mechanism for effecting a predetermined extent of operation of the platen and therefore the bill form will be line spaced for each item listing operation.

20 It will be seen that the operating connections of the bill feed attachment to the accounting machine are detachable and very simple which makes it an easy matter to connect the attachment to the accounting machine. It is plain that these simple connections make it possible to attach the bill feed attachment to accounting machines other than the one shown, such as any motor operated adding machine in which banks of type-bars like 25 cooperate with a platen to print items and totals. The bill feed mechanical parts are of the kind disclosed in the U. S. Patents No. 2,046,001, No. 2,110,853 and No. 2,126,644.

25 The bill feed attachment is a self-contained unit, the entire mechanism of which is supported by a rigid frame work comprising right and left side frames 35, 36 (Figs. 1 to 3), respectively, a vertical cross frame 37 (Fig. 3), a horizontal cross frame 38, and several cross bars such as 39 and 41. This frame work is pivotally mounted on two brackets such as 21a (Fig. 1), secured to frame 20, the pivots being a shaft 46 carried by the brackets. The shaft 46 may be adjusted vertically and horizontally by means of four adjusting screws carried by the brackets. Thus any slight inaccuracies in the machining of the parts may be compensated for and the bill feed attachment accurately aligned with respect to the type-bars 25.

30 The bills are designated 48 in Figs. 1 to 3 and are relatively greater in width than in length, like those commonly used by public utility corporations in billing for public services. These bills have printed headings, advertising matter, general information, service rates, and so on, printed on the face and back, and also have suitable blank spaces or lines for the printing of items and totals by type-bars 25.

35 The supply hopper for the blank bills is formed by the rear face of cross frame 37 (Fig. 3), the top face of cross frame 38, two side plates 49, and several vertical posts 50 secured to the rear edge of frame 38, which form an open pocket in which the bills are placed face down with the top edges of the bills to the left.

40 The posts 50 are secured by screws (not shown) to spacer blocks 56 (Fig. 3) which are attached to the edge of frame 38 by screws 57. By substituting blocks 56 of various thicknesses, the

bill feeding attachment may be accommodated to bills of different lengths.

45 A weight is provided to keep the bills flat in the supply hopper. This weight is composed of two flat plates 58 (Fig. 3) joined by a cross bar 59 to the center of which is attached a knob 60 by means of which the weight may be lifted. Plates 58 have tongues 61 formed therein which are guided in rectangular grooves in posts 50.

50 The bills are removed from the supply hopper one at a time by means of a picker mechanism which includes a number of picker slides 62 reciprocable in guides 63 secured to frame 38. A picker 64 is mounted on the rear end of each slide 62 by spacer blocks 64a and an adjustment screw 64b which picker projects upwardly a distance slightly less than the thickness of a bill so as to push the bill at the bottom of the hopper toward the left (Fig. 3) each time the picker slides 62 move in that direction. By substituting spacer blocks 64a of different lengths, the picker mechanism may be adapted to feed bills of different lengths.

55 The supply hopper is also provided with a number of throat knives 65 adjustably secured by screws in vertical slots cut in the rear wall of frame 37 adjacent the lower edge of said frame. Coacting with these throat knives 65 are throat blocks 68 which are adjustably mounted in slots in the top face of frame 38 by means of screws. As many of these throat knives and blocks as may be necessary may be provided. They are adjusted relative to each other to provide a narrow gap or throat between their ends just sufficient to permit the bill at the bottom of the hopper to pass to the left when pushed in that direction by slides 62 and pickers 64.

60 The slides 62 carrying pickers 64 are operated by means of gear sectors 70 adjustably mounted on a shaft 71 which is journaled in frames 35, 36. An arm 72 (Fig. 1) is also adjustably secured to shaft 71 outside of frame 35 and to said arm is pivoted a link 73 which is pivoted to a gear 74 by means of a screw stud which is threaded into the hub of gear 74. The latter is secured to the outer end of a stub shaft 75 journaled in two spaced sub-frames 76, 77 secured to each other and to frame 35. A gear 78 secured to the left or inner end of shaft 75 meshes with a gear 79 secured to a second stub shaft 80 also journaled in frames 76, 77. Fixed to shaft 80 is a gear 81 which meshes with an idler gear 82 loosely mounted on a stud 83 fixed to a frame 84 (Fig. 1). This frame is adjustably mounted on the right side frame 21 by means of screws which pass through slots in frame 84 and are threaded into frame 21. Shaft 27 extends through a hole in frame 84 and mounted on shaft 27 is the clutch gear 85 meshing with gear 82 and activated by the bill feed magnet BF as noted hereinbefore.

65 The ratio of the gearing just described is such that stub shafts 75 and 80 turn one revolution for two revolutions of shaft 27. Thus the slides 62 will move forward (to the left, Fig. 3) during the first half revolution of shaft 27 to push the bill at the bottom of the hopper to the left through the throat formed by throat knives 65 and throat blocks 68.

70 Each bill removed from the bottom of the hopper by pickers 64 is carried to the left (Fig. 3) far enough to be gripped by the first set of grooved feed rollers 88, 89. Roller 88 rests upon roller 89 and is spring pressed against roller 89 by means of a number of pressure shoes having shanks loosely received in holes in the lower ends of studs

91 adjustably mounted in a cross bar 92 secured to frames 35, 36. Springs 93, interposed between shoulders in studs 91 and the shoes, press the latter down into the grooves in the roller 88 thereby holding rollers 88, 89 firmly in contact.

The roller 89 is journalled in bearings in the frames 35, 36 and is geared to roller 88 by means of pinions 94 (Fig. 2) and 97 secured to the ends of rollers 88, 89 which extend outside frame 36.

A second set of feed rollers 98, 99 is provided to the left of rollers 88, 89 (Fig. 3) and are identically constructed and mounted. The pressure shoes for rollers 98, 99 are slightly differently constructed although the principle of operation remains the same. Parallel with roller 98 is a shaft 100 secured to frames 35, 36 and loosely mounted on the shaft 100, between collars secured to said shaft, are a number of pressure shoes 102. A torsion spring, surrounding shaft 100 between each shoe 102 and one of collars, has its ends projecting into holes in the collar and shoe, respectively, and has the effect of forcing the end of the shoe down into a groove in roller 98 thus pressing rollers 98, 99 firmly together.

A pair of pinions 94 (Fig. 2) are provided for rollers 98, 99, as in the case of rollers 88, 89, and a pinion 97 is also provided on the left end of roller 99. The pinions 97 of rollers 89, 99 both mesh with an idler gear 104 journalled on a stud carried by frame 36. A pinion 105 (Fig. 1) secured to roller shaft 99 meshes with driving gear 74, and the ratio of the gearing comprising gears 74 and 105, and pinions 97 and 94 is such that the rollers 89, 99 make two revolutions per revolution of gears 74 and 79 in a direction to carry a bill to the left after it has been advanced from the supply hopper by picker 64. A blank bill 48 is thus advanced from the hopper and its top or leading edge carried to position to the left (Fig. 3) of rollers 98, 99, but short of the bill lever 101, during the revolution of shaft 27. Early in the next advance of the bill toward the platen, lever 101 is rocked and bill lever contacts BLC are closed.

Third and fourth sets of feed rollers 106, 107 are provided, which rollers are similar in all respects to the rollers 98, 99 except that the relation of the rollers and their pressure shoes is reversed. The right-hand ends of rollers 106, 107 are provided with meshed pinions 108, 109 (Fig. 1) similar to pinions 94, 97 (Fig. 2), but the pinions 109 (Fig. 1) mesh with a small idler gear 103 and a large idler gear 110 journalled on a stud 111 carried by frame 35. On the left (Fig. 2), a pinion 211 is on the shaft of a roller 107 and meshes with an idler 210 driven by gear 261. The train of driving connections to gear 110 is pointed out hereinafter.

Referring again to Fig. 3, it is noted that the bill 48 in passing between rollers 88, 89 and 98, 99, passes between a line of sensing brushes 282 and a cooperating contact roller 281. The brushes 282 sense the bill perforations representing an account number or such an identifying designation. The account number data is inverted and put into a relay storage and comparing device wherein a supposedly related account number from a record card is also entered for comparing purposes. As noted later in connection with the wiring diagram, the result of the comparison is used to govern the machine and the bill feed devices.

Mounted outside the frame 36 (Fig. 2) is a pair of circuit breaking bill feed cam contacts BF-1 and BF12 relating to the bill feed sensing circuits.

They are driven by gears 86, one of which meshes with a small idler gear 87 that is in mesh with a driven gear 261 which is the part driven along with gears 94 and 97 by means of the gear 260 on roller shaft 99.

A platen 112 is provided (Fig. 3) which is secured to the shaft 113 and has the usual knobs 114 (Fig. 1) secured to said shaft by means of which knobs the platen may be turned manually. The shaft 113 is mounted in ball or roller bearings which are mounted in carriers pressed into holes in the frames 35, 36. A gear 153 is fixed to the right-hand end of shaft 113. The platen 112, as is usual in accounting machines, has a surface of resilient material such as rubber to permit clear impressions to be had from the types on type-bars 25. Extending parallel with platen 112 and beneath it is a shaft 119 (Fig. 3) which may be provided with a number of rolls 120 of resilient material. Shaft 119 is mounted in arms and is provided with pressure shoes 102 on a shaft 101 extending parallel with the platen 112 and secured to frames 35, 36. Secured to shaft 119 is a pinion 121 (Fig. 1) which meshes with gear 153.

Journalled in frames 35, 36 above platen 112 is a shaft 122 (Fig. 3) which has mounted thereon a series of rubber rollers 123 for bill feed control.

Cooperating with rollers 123 is a roller 124, preferably made of polished steel, which is journalled in arms and pressed against rollers 123. A pressure shoe 102 at each end of roller 124 adjacent frames 35, 36 presses the latter firmly against rollers. A pair of pinions 125, 126 (Fig. 2) similar to pinions 94 provide a driving connection between shaft 122 and roll 124 at their left-hand ends. Gear teeth 127 in a driven clutch element secured to shaft 113 mesh with pinion 126. It will be plain that rotation of platen shaft 113 in a clockwise direction (Fig. 3) will cause platen 112, shafts 119 and 122, and feed rollers 120, 123, 124 to rotate together and to feed a bill from a print receiving position around the platen, upward to be engaged by the stacker drum 204.

Rotatably mounted on a stud 129 (Fig. 1) carried by frame 35 is driven clutch element 130 provided with gear teeth 131 which mesh with a gear pinion 132 secured to gear 110. The driven clutch element 130 is recessed to receive a clutch driving element 133 which is loosely mounted on the hub of element 130.

Secured to element 133 is an arm 134 to which is pivoted a jointed adjustable linkage 135-135' which is pivoted at its lower end on a crank pin 136 secured at right angles to the end of a rod lying in a slot 138 cut lengthwise of a bar 139 fixed to the outer end of stub shaft 80. The upper end of the rod is threaded into a tube loose in a hole bored lengthwise of the upper end of bar 139. The latter has a rectangular notch in which is a knurled bushing 143. Obviously, rotation of bushing 143 manually in the appropriate direction will cause crank pin 136 to be set either up or down in slot 138.

The head of crank pin 136 fits loosely in the T slot 138 and projects through the open part of such slot. Loose on the outer or right-hand end of the crank pin 136 is a bushing having a shallow lug milled therein which rides in the open part of the T slot 138. Link 135 has a bushing 145 of bearing metal secured to its lower end which fits the bushing loosely. A washer interposed between bushing 145 and the nut on the crank pin retains the link 135 loosely on the

bushing. When the nut on crank pin 136 is tightened, the head of said crank pin and the bushing 144 are forced toward each other to clamp the pin to bar 139, thus firmly holding said crank pin in the position to which it has been moved by turning bushing 143. Thus no strain is placed on the adjustment parts when the bar 139 is rotated by stub shaft 80 during the operation of the bill feed attachment.

Inside the clutch housing 130 is the usual form of hardened roller clutch affording a clamping action in one direction for the driving element 133. This clamping or wedging action of the interior rollers locks the elements 130, 133 together and causes the former to be rotated each time link 135 is drawn downwardly by crank pin 136. On the upstroke of link 135 the driving element 133 rotates in a counterclockwise direction and the rollers have a tendency to be unclamped and move away from element 130 so that element 133 merely turns idly without turning element 130.

The bar 139 is so positioned on shaft 80 that the crank pin 136 and link 135 move upwardly to their upper position during the first half revolution of shaft 80, which it will be remembered makes one revolution each time the clutch 13 and shaft 27 makes two revolutions. During the next half revolution of the drive shaft, link 135 and crank pin 136 move downwardly to their lower dead center position. While this movement is taking place (Fig. 3), feed roller 120, platen 112, and feed rollers 123, 124 will be driven by element 130 (Fig. 1) through the train of gears comprising gears 132, 110, a gear 153 loosely mounted on shaft 113, a clutch 154 which is normally engaged, gears 118, 127, and pinions 121, 126, and 125. A bill between rollers 98 and 107 will be carried to the platen while one at the platen will be fed to the stacker drum.

The platen clutch 154 is practically identical in construction with the clutch including elements 130, 133, except that in clutch 154, the recessed element is the driving element and the inner element is the driven element and is secured to shaft 113. The platen clutch 154 permits turning the platen forwardly by hand to feed a bill from the platen up to the stacker without rotating the gearing between platen gears and element 130.

It has been found that there is a tendency for the clutch driven element 130 to rotate backwardly on the upward stroke of link 135 due to the friction of the driven element 130 and driving element 133 and connected parts, just enough to take up the slack in the gearing between the clutch and platen. Accordingly a brake device is provided to apply sufficient friction to driven element 130 to prevent the friction in the clutch parts from causing element 130 to rotate backwardly.

It may be necessary to turn the platen backwardly by means of a knob 114. Were no means provided to disengage either clutch 154 or the clutch comprising elements 130, 133, it would be difficult, if not impossible, to turn the platen backwardly by means of a knob 114 as this would result in rotating the gearing to element 130, element 133, crank 136, 139, gears 79, 81, 82, 85 and clutch shaft 27 backwardly. Rotation of the latter shaft backwardly would disarrange the timing of the mechanism and be likely to damage certain cam actuated contacts operated by the shaft.

These evils are overcome by the devices for disengaging clutch 130, 133 and advancing an attached disk 161 thereon by means of manipu-

lative lever 169 and pawl 175 as explained in detail in U. S. Patent 2,046,001.

Bills, in travelling from right to left (Fig. 3) from the supply hopper to the platen, are supported between the feed rollers 88, 89, 98, 99, 106, 107 by means of a series of guide plates designated 180a to 180d. Guides 180b, 180c meet beneath rollers 98, 99. Guide 180a is supported by bar 43. The right-hand edge of guide 180a is slanted to ensure that bills delivered by the picker mechanism to rollers 88, 89 will pass over said guide and not underneath. All of these various guides are apertured or slotted to permit the various feed rolls to contact.

The guide 180d curves forwardly and upwardly close to the platen 112 for a distance of approximately one fourth the circumference of the platen and terminates, for the greater part of its width, in a bevel just below the printing line P. Adjacent frames 35, 36, and at the ends of platen 112, guide 180d has tabs which extend upwardly a further distance as in Fig. 12.

The bill is guided from the printing line P to feed rollers 123d, 124 by a paper guide and inking ribbon guard best illustrated in Fig. 3. Extending crosswise of the bill feed attachment above and below platen 112 between frames 35, 36 are two bars 181, 182. Bar 181 is secured to frames 35, 36 and beveled in front of the curved edge of guide 180d to provide room for said guide and is provided with grooves at spaced intervals to correspond with the narrow spaces between the type-bars 25.

Bar 182 is roughly triangular in shape, the apexes of two of the angles being slightly flattened and one of the faces of said bar opposite platen 112 is provided with long V-shaped notches or grooves in the same plane as the grooves in bar 181. Into the grooves are laid guide elements 185 which are preferably made of wire bent to the shape concentric with the platen periphery.

Several cycles of operation of the clutch on shaft 27 are required before the first bill in the supply hopper reaches the platen and is in position to receive the first printed item. The first cycle carries the first bill over to project just to the left of roller 98 (Fig. 3). During the first half of the next cycle, the bill is carried further to the left so that the leading edge reaches rollers 107 and 106. During the second cycle, a second bill is advanced out of the hopper to replace the first bill. Both of these bills are fed by the feed rollers 88, 89, and 98, 99; and rollers 106, 107.

During the second half of the second cycle, feed rollers 106, 107, carry the first bill to where the leading edge is just approaching the platen.

During the third cycle of operation, a third bill is introduced, and the first bill is buckled against the platen by rolls 106 and 107 which are running while the platen is stationary. Then rollers 120, platen 112, and feed rollers 123, 124 are turned by action of crank 136, 139, linkage 135, 135', arm 134 and clutch 130, 133 and carry the first bill to where the leading edge is just above the printing line on the platen. By adjusting pin 136 away from the center of shaft 80 the distance the bill is fed above the printing line is increased.

During the fourth cycle of operation, a fourth bill is introduced and the first bill is projected upward by rollers 123, 124 so that its leading edge can be grasped by the finger 227 on the stacker drum 204.

The stacker is best shown in Fig. 3 while its driving connections are best shown in Fig. 1. The left end of the stacker drum 204 is secured to a spider 205 which is loosely mounted on a shaft 206 journalled in frame 36 and at the right end, there is a similar spider. Shaft 206 has an adjusting means 207 (Fig. 2) outside frame 36. Outside the frame 35 (Fig. 1) is a gear 212 with connections to the stacker drum 204.

Stacker gear 212 meshes with an idler gear 217 which in turn meshes with a large gear 218. This gear has four radial grooves 219 and in an outer end of one of these grooves, there normally lies one of two rollers 220 carried on a gear 221. The latter is journalled on a stud 222 carried by frame 35 and has a Geneva locking plate 223 adapted to cooperate with locking surfaces 224 on gear 218. Gear 221 meshes with a pinion 225 secured to a gear 226 which meshes with the pinion 105. The ratios of the various gears just described is such that gear 221 makes one half revolution per cycle of operation of the driving means. During the first half cycle of the driving operation one of the rollers 220 will rotate gear 218 one quarter of a revolution. The ratio between gears 212, 217 and 218 is such that stacker drum 204 will turn one half of a revolution for each quarter revolution of gear 218. In other words, the drum 204 turns one half revolution during the first half driving cycle and is idle during the remainder of the cycle.

The stacker drum 204 is provided with two sets of stacker fingers 227. There are four fingers to each set of fingers and the sets are locked on opposite sides of the drum. The fingers of each set project through openings in drum 204 and are secured to a casting 229 pivoted at 230 to the interior of drum 204. Springs 231 normally tend to rock the castings 229 in a direction to cause all fingers of each set to press against the surface of drum 204 adjacent the openings. The castings have cam extensions by means of which the fingers 227 are raised and lowered by the action of two cam rollers 233 and 234. The rollers are carried by adjustable arms 236 rotatably mounted on shaft 206.

Arms 236 are so adjusted that with the stacker drum in the normal position of Fig. 3, the extending ends of the upper set of fingers 227 will be held away from the drum 204 by roller 233. When the fingers 227 are so positioned, a bill fed upward by rollers 123 and 124 will advance so that the leading edge of the bill is between the periphery of the drum 204 and the ends of fingers 227. As soon as the stacker drum starts to turn, the fingers 227 are lowered to grasp the bill and clamp it on the drum where it is carried clockwise around into the stacking position.

Mounted on cross bar 37 is a plate 237 which, with the inside faces of frames 35 and 36, forms the storage hopper for the printed bills. The forward or left end of plate 237 is provided with upturned extensions which project into grooves in drum 204 to limit the movement of the bill around with the drum.

The inside faces of frames 35 and 36 are formed with grooves 240 which act as tracks for a follower plate 241 carried by brackets 242 having rollers which ride in the groove 240. Since the grooves 240 are inclined downwardly the follower plate tends to press against drum 204 the bills 48 accumulated on the top of plate 237.

The line spacing mechanisms for both item and total printing are provided and are best shown in Figs. 1 and 2. It is already explained

hereinbefore with reference to Fig. 1 how the line space magnet LSM controls platen movement for line spacing under control of impulses originating mainly in the tabulator.

Additional line spacing mechanism is provided which may be used to supplement that just described only during bill feeding cycles and total printing operations. This mechanism is driven by the feed roller 99 (Fig. 2) secured to which is a pinion 260 meshing with a larger gear 261 journalled on a stud carried by frame 36. A T-slot is formed in gear 261 which carries a T-block adjustable in said slot. One end of a link 262 is pivoted to the sliding block by means of the screw 261a which is used to clamp the block in adjusted position. The other end of link 262 is formed as a rack in mesh with a gear 263 rockably mounted on a stud 274 secured to frame 36. Gear 263 is secured to the driving element of a clutch identical in principle of construction with clutches on stud 129 and platen shaft 113 as described in Patent No. 2,046,001. The driven element 267 of the clutch is secured to an element 268 shaped like a cam and having a notch 269 and a shoulder 270. Also loosely mounted on stud 264 is a gear 271 having a pin 272 which may occupy a position just in front of shoulder 270. Gear 271 meshes with gear teeth 273 in the periphery of the platen clutch element 255, and is held on by a screw 274. By loosening screw 274, gear 271 can be slid outwardly on a stud far enough to disengage pin 272 from the shoulder 270 of element 268 and place said pin in notch 269, or vice versa.

Coacting with the outer surface of element 267 of the clutch is a brake shoe 275 pivoted at 276 to frame 36. Secured to brake shoe 275 is an extension extending upwardly and rearwardly parallel with frame 36 and attached to the free end of this extension and to a pin carried by said frame is a spring 278 which keeps the brake shoe in contact with element 267.

Gear 261 rotates a full revolution during one cycle of the bill feed operation. During the first half of such revolution, link 262 moves forwardly rocking gear 263 in the same direction an angular distance depending on the distance of pivot screw 261a from the center of gear 261. Element 268 will be rocked a corresponding amount and if pin 272 is in slot 269, gear 271 will be positively rotated by said element thereby rotating platen 112 through the clutch an amount determined by the adjustment of link 262. Thus, the totals will be spaced a constant distance from the last item for each setting of link 262. Obviously the greater the distance to screw 261a from the center of gear 261 the greater will be the amount the platen is rotated. The maximum amount of rotation imparted to platen 112 by the line spacing mechanism driven by gear 261 is considerably greater than the maximum rotation which can be produced by the line spacing mechanism controlled by magnet LSM.

When it is desired to line space items and totals alike, link 262 is adjusted so that the screw 261a is concentric with gear 261 so that only the line spacing mechanism operated by magnet LSM will be effective.

If it is desired that totals be spaced from items a greater distance than that separating items, link 262 is adjusted so that screw 261a is eccentric the proper amount to produce the desired spacing between the last item and the total. Both line spacing mechanisms will operate together but due to the type of clutches used, the faster

of the two mechanisms will predominate. In other words, if link 262 is adjusted to rotate the platen a greater distance than link 251, the movement of the latter will be merely idle. On the other hand, if link 251 is adjusted to rotate the platen more than link 262, the movement of the latter will be idle.

The pivot screw 261a need only be set a slight amount eccentric to gear 261 in order to produce a space after the last item greater than the space which is produced by link 251 and its operating connections.

When it is desired to print the total always on a predetermined line of the bill irrespective of the number of items, instead of at a constant distance from the last item, the pin 272 is placed in the position of Fig. 2, i. e., adjacent shoulder 270. As items are printed, pin 272 will travel in a clockwise direction (Fig. 2) an increment for each item, due to rotation of gear 271 by platen shaft clutch elements. When the total cycle takes place, link 262 will move forwardly and rock gear 263 and clutch element 267, and disk 268 a fixed amount. At some point in this movement, shoulder 270 will strike pin 272 and rotate gear 271 until link 262 reaches the end of its forward motion.

The platen will be turned a variable amount by the movement, depending on the number of items previously printed but will be arrested at a point determined by the position of screw 261a. The total will always be printed on the same line of the bill.

During the last half of each revolution of the bill feed drive the link 262 and connected parts are restored to the position of Fig. 2. The brake shoe 275 exerts sufficient frictional force to prevent displacement of element 267 when gear 263 is restored to the position of Fig. 2, and it also serves to prevent overthrow of the clutch element 267.

It should be noted that element 268 and pin 272 are not restored to the position of Fig. 2 but are left in a new position each time link 262 and gear 263 are restored. This does no harm as the only conditions to be satisfied are that pin 272 should be in notch 269 or abutting shoulder 270 at the end of each bill feeding cycle. These conditions are always satisfied by the manner of operating element 268 without the need of special restoring devices or mechanisms.

Naturally it is necessary to adjust the line spacing mechanisms so that when it is desired to print totals on a predetermined line, pin 272 should be in notch 269 or abutting shoulder 270. This is accomplished by adjusting link 251 according to the number of items to be printed in the space allotted to items which must be enough less than the maximum feed imparted by link 262 to leave room for the total.

Referring to Fig. 2, it is seen that another brake 259 is applied to the platen clutch as a line shaft brake. This brake is on the lower end of a lever 207 pivoted at 202 and pulled into operation by a spring 208.

A pressure release device for roller 120 (Fig. 3) is provided in the form of a positionable lever 213 (Fig. 1) fulcrumed on an extension 214 of the roller holder shaft 101. The bracket 211 provides locating notches for the "on" and "off" positions of the knob on the end of the pressure relief lever 213.

The foregoing section of the description is concerned mainly with the mechanical aspect of the bill feeding devices. The following portion of

this specification is devoted to consideration of the electrical controls of the tabulator first, and then the effect that the card group control devices and bill account number comparing devices have over the operation of the bill feed devices and the tabulator. As shown in the wiring diagram, Figs. 13a-13e, the controls of the bill feed device are coordinated for equal, non-equal control with the devices of an alphabet printing tabulator. The tabulator is of the type disclosed in U. S. Patents No. 2,079,418 and 2,172,067 and 2,199,547 and application Serial No. 609,854, filed August 9, 1945, to which reference may be made for the details of construction. Before describing the manner in which the bill sensing and comparing devices enter into the controls it is believed well to first outline some of usual tabulator features.

In such machines a motor TM (Fig. 13a) is connected to communicate a drive through two clutches which are selectively operated for card feeding and printing operations. A number of CF cam contacts operate only when the card feed clutch is engaged. Certain PM contacts operate only when the printer clutch is engaged. Other CB contacts operate all the time that the motor is active. A series of TS contacts are operated only when a total taking cycle is initiated.

After record cards R, such as those shown in Fig. 4, are placed in the feed magazine, in initial feeding cycle is brought about by pressing a start key to connect the card feed clutch devices. The circuit passes from line 320 (Fig. 13a), wire 300, the stop key contacts SP, the start key contacts ST, wire 301, pickup coil of R12, and line 321. Relay R11 will now be picked up through a circuit from line 320, wire 302, cam contacts CB31, R61c, R63b, R12d now closed, normally closed C1AL and CC23-2, pickup coil of R11, wires 303, 304 and line 321. When R11 is picked up, the card feed clutch will be energized by a circuit from line 320, wire 305, wire 306, R11c points now closed, the card feed clutch magnet CFCM, wire 307 and line 321. The card feed clutch will engage at 330° in the cycle and start the record cards through the tabulator feed rolls 308-311 (Fig. 4).

When the card feed clutch magnet CFCM is picked up, a parallel circuit is set up through R61a, the pickup coil of relay R15, wire 312 and line 321. Relay R15 picks up relay R16 which, in turn, closes contacts R16A to call in the print clutch magnet PCM.

As card feeding starts, a cam contact CF9 (Fig. 13e), closes to call in a relay R1. The circuit passes through line 320, circuit breaker contacts CB1-4, relay contacts C5AL, timer contacts CF17, CF18, contacts R2a, common brush 329, the upper brush contact roll 330, brush 331, upper contacts R6B, cam contacts CF9, the pickup coil of relay R1, wire 333 and line 321. Relay R1 is then held through contacts R1a and CF8 until the first full cycle is well advanced.

Relay R1 is effective to open contacts and de-energize the connections to the card feed clutch. Thus, the card feed mechanism is operated for one cycle and then stopped.

Under initial starting conditions it is necessary to depress the start key a second time to cause a continuous succession of card feed cycles. As soon as cards continue to feed and insulate the brush 331, relay R1 remains de-energized and certain of its contacts remain closed to maintain the holding circuit for the card feed clutch con-

trols. Another relay R2 is connected with relay R1 to control contacts at various points in the machine in the nature of an upper card lever control.

The lower card lever relays R3, R4 and C1 (Fig. 13a) are energized when the first card passes below the upper brushes UB and they remain energized until the last card passes the lower brushes LB. The first card closes the lower card lever contacts LCLC after digit analysis under the upper brushes. The cam contacts CF6 also close to energize the relays by the circuit: Line 320, wire 305, cam contacts CF6, card lever contacts LCLC, relay R3, R4 and C1, wire 304 and line 321.

On the second feeding cycle, relay R16 (Fig. 13a) is energized by a circuit involving line 320, wire 313, R3b now closed, wire 315 to switch S1, through S1, R15A now closed, the pickup coil of relay R16 and line 321.

As a result, the print clutch magnet PCM is picked up by a circuit involving line 320, wires 305 and 314, R11c now closed, R16A now closed, print clutch magnet PCM and line 321. The clutch is therefore unlatched and ready to engage at 330° and start the type-bars up in synchronism with the movement of first card passing the lower brushes.

In listing operations the record card passes the lower brushes LB in synchronism with the upward movement of the type-bars. Magnets 23 (Fig. 3) operate stop pawls to locate the type-bars in positions corresponding to the data punched in the card and at a predetermined time, hammers are tripped to record the information on the bill record 48. Adjustment of the type-bars is regulated by impulses carried to magnets 23 from the lower brushes LB. An illustrative printing control circuit involves line 320 (Fig. 13e), contact breakers CB1-4, contacts C5AL, timer contacts CF17 and CF18, lower card lever relay contacts R4a, common brush 345, contact roller 347, through the perforation in the card by a lower brush LB, the brush socket, a plug wire to socket A1, normally closed contacts TSa, magnet 23 and line 321.

Contacts TSa are shifted for total cycles so that printing is then controlled by impulses from an accumulator rather than from the lower brushes.

Group control devices are provided for separately considering different classes or groups of cards as distinguished by different group number perforations for different groups. Consecutive cards are compared, one card being read at the upper brushes while the preceding card is read at the lower brushes. As long as the card readings are alike, the card feed continues to function. When the machine senses that the two group readings are not alike, the feed unit stops, the machine prints the total, the accumulator is cleared to zero, the bill form is replaced, and the machine automatically starts feeding the cards of the next group.

Preliminary to the establishment of group control circuits, a number of preparatory relays R169-R175 (Fig. 13c) are energized to close the circuits for the comparison relays. The preparatory circuit includes line 320, wire 316, cam contacts CF19, relays R169-R175, wire 317 and line 321. As an example of the effect of these relays, it is seen that relay R169 serves to close contacts R169B in series with the group control pickup coils R129-R133.

The actual comparing circuits are connected by plug wiring between comparing relay pickup

coils and certain upper and lower brushes devoted to sensing group numbers or special perforations. An example of the comparing circuits is as follows: Line 320 (Fig. 13e), contacts CB1-CB4,

5 contacts C5AL, timer contacts CF17 and CF18, contacts R2a, common brush 329, contact roller 330, through the perforation in the card sensed by the upper brush UB, plug wire connected from a socket in line with the upper brush to a socket 10 388 (Fig. 13c) in line with the pickup coil of relay R129, contacts R169B and wire 369 to line 321. As long as group numbers agree, a companion circuit to that already traced is set up at the same time through a pickup coil of a relay R130 as 15 energized through the lower brushes by the following circuit: Line 320 (Fig. 13e), contacts CB1-CB4, contacts C5AL, contacts CF17 and CF18, relay contacts R4a, common brush 345, contact roller 347, through a perforation in the 20 card sensed by the lower brush LB, a plugwire connected to socket 390 (Fig. 13c), pickup coil of relay R130, contacts R172A and line 321.

Relays R129 and R130 have holding coils and contacts in series therewith for sustaining the 25 comparing circuit connections. The holding circuit includes line 320, CF21, wire 381, contacts R129A, the holding coil of relay R129 and line 321. In a similar fashion the other pairs of holding coils, such as those of relays R133, R134 are 30 picked up and held as a part of the comparing control.

Referring to the upper left-hand part of Fig. 13c, it is seen that the pairs of comparing relays are associated with pairs of contacts so arranged 35 that, when a related pair such as relays R129 and R130 are energized at the same time, they fail to provide a circuit path. However, should one or the other be energized alone, showing that there is a disagreement in the group control perforations, then a circuit is established for setting up a minor control operation: Line 320, cam contacts CB17, CB18, the left contacts R129B, the right contacts R130B, a plug wire connection between the orders and socket 385, plug wire to socket MI Shunt (Fig. 13b), the pickup coil of relay R53, wire 350 and line 321. A holding circuit is established for relay R53 due to the closure of contact R53A in series with the holding coil. The holding coil of relay R53 operates other contacts R53B in series with a minor control pickup coil of a relay R61. The minor control circuit includes line 320, cam contacts CB19, lower card lever relay contacts R3b, relay contacts R53b, switch S4, the pickup coil of relay R61, wire 392 and line 321.

55 55 A holding circuit is established for relay R61 by the closure of contacts R61a and connections which may be traced from line 320, wire 323, cam contacts PM15, contacts R61a, relay R61, wire 392 and line 321. Associated with relay R61 are other minor control relays R62-R65 which are energized along with it. These relays have contacts throughout the machine for controlling the suspension of card feeding, the initiation of total taking, etc.

65 65 The foregoing description of the group control comparison and the resulting pickup of minor relays for control purposes is duplicated with respect to other columns or groups of columns on the record cards for intermediate and major control. The particular columns selected for control are made effective by plugging from various sockets, such as 385 to the sockets INT Shunt and MAJ Shunt. Then the intermediate relay 70 R54 and major control relay R55 are called into 75

action to set up circuits for relays R67 and R13 similar to that of the minor control described in connection with energization of relay R61. Associated with intermediate relay R67 is another control relay R68.

Referring to the lower left hand corner of Fig. 13b, it is seen that the machine is equipped with a digit selector DS, which is mounted on the shaft of the CF contact unit and therefore the emitter turns only when the card feed unit is in operation. The digit selector emitter has 12 segments, one corresponding to each of the 12 perforation positions on the card. The common brush 324, which is connected to the digit selector common hub DSC, makes contact on the 9 segment at the same time that an upper (or lower) brush would read a 9-hole, and makes on the 8 segment at 8 time, etc. Therefore, if the DSC hub is wired to an upper (or lower) brush, an impulse through a 9-hole in that column would come through to the digit selector 9 hub; an impulse through an 8-hole would come to the 8 digit selector hub, etc.

By this means the punching in a column may be selected, and each digit may be directed, as desired, to operate various circuits.

The circuit arrangements mentioned hereinbefore deal mainly with the control of the tabulator, while those about to follow are concerned more with controls reaching into the bill feed device to operate magnet LSM for line spacing and bill feed clutch magnet BF for long feeding and bill ejection.

It will be realized that the circuits about to be traced for line spacing and ejection control are not all the circuits possible to exercise control thereover. These circuits given are pertinent to the present invention and all that are necessary for an understanding thereof.

The line spacing control for ordinary listing operation provides a circuit through magnet LSM when printer cam contacts PM11 close after each printer operation. The circuit for list spacing includes line 320 (Fig. 13b), wire 325, printer cam contact PM11, relay contacts C6B normally closed, magnet LSM and wire 326 connected to line 321. This circuit will effect line spacing for the items listed in the body portion of bill form 48.

When the last item is listed and a no X-X change is detected between the last item card and the first heading card of a group, the tabulator will be conditioned to print a minor total through a plugwire connection between the socket of the upper brush UB sensing the X perforation in the heading card to the socket labeled MI Shunt (Fig. 13b).

Before explaining the wiring controls of the bill feed involving the relay storage devices for account number indicia and the comparing devices for determining the equal or no-equal relationship between card and bill, it is believed well to note the relative positions of the related cards and bills in the tabulator and bill feed device, respectively, as shown diagrammatically in Figs. 4, 5 and 6. There it is seen that as the first bill form 48 is advanced out of the bill hopper, the account number is sensed by brushes 282 and put in the pickup side of the relay storage devices. Meanwhile the first card R is advanced just short of the upper brushes UB.

On the second cycle (Fig. 5), the first card is read under the upper brushes UB and the reading is spilled into the comparing device where it is compared with the reading of the first bill as taken from the secondary or bottom holding

section of the relay storage unit. Meanwhile a reading of the second bill is being directed into the primary or pickup side of the relay storage unit. The first bill by that time is advanced to a position just short of the platen 112.

Assuming there is agreement and equality of account numbers, the third cycle (Fig. 6) finds the first bill around the platen for print reception. The second bill is in the intermediate position just short of the platen and its account number is being taken out of the secondary part of the storage unit and compared with the second record card being read under the upper brushes UB. The first card is passing under the lower brushes LB where control of the printer is exercised to print on the first bill at the platen. The third bill in the meantime is being sensed and the reading directed into the primary side of the relay storage unit.

20 Of course, Figs. 4, 5 and 6 assume conditions of an ideal and elementary nature as when there is a one to one card and bill arrangement. Other conditions prevail when a series of cards relate to one bill and then the bill feed must be suspended as long as the group control devices of the tabulator sense that a succession of cards is of one account. Another variation is found when either card or bill is missing or out of order in which case the comparing device finds a no-equal condition on account of numbers and the machine is stopped and a signal lighted. Then both the card and bill feed hoppers are emptied by use of the operating keys and printing is suppressed during the runout.

35 Depression of the start key (Fig. 13a) and closure of contacts ST calls in relay R12, and that in turn, through closure of contacts R12d, calls in both relays R11 and C4 for operating both the card feed and the bill feed. The card feed clutch magnet CFCM is operated when contacts R11c close by a circuit including line 320, wires 305, 306, contacts R11c, magnet CFCM and wire 307 to line 321. The printer clutch magnet PCM and the bill feed clutch magnet BF are energized through closure of C4BL and C4AL. The bill feed clutch circuit includes line 320, wires 319 and 327, C4AL, CBC3, BF-1, wire 328, magnet BF and line 321. In parallel therewith, through contacts C4BL, the printer clutch magnet PCM is energized. Bills and cards are fed together at the start of the run for two cycles and then the first card has reached a position ready to go through the lower brushes (Fig. 5).

55 Near the end of the second card feed cycle, the auxiliary lower card lever relay C1 is picked up along with the usual lever control relays R3 and R4 as follows: line 320, wire 305, cam contacts CF6, lower card lever contacts LCLC, relays R3, R4, C1, wire 304 and line 321. By opening contacts C1AL (Fig. 13a), relay C1 breaks the circuit to the R11 and C4 relays. After this cycle, the circuits to the card feed control R11 are dependent on the CC21-3 contacts of the bill feed. Then a circuit to energize the bill feed clutch is directed through contacts C1-AU and C3B which is picked up by a digit, cycle or total eject impulse. The print clutch is energized through contacts R16-A in normal fashion. Contacts C1-AU prevent ejection without cards 60 when controlling. The C1-BL contacts provide a circuit path to relay C4 to run out the bills by depression of the runout key when a hopper is empty.

70 A relay CC21 (Fig. 13b) is operated by the bill feed lever contacts BLC (Fig. 3) as a control for

determining the presence and passage of a bill between rollers 98 and 107 and for connecting various circuits dependent on presence of bills. The bill sensing circuit passes through line 320, wire 334, contacts BF4, bill lever contacts BLC, magnet CC21 and wire 335 to line 321. Bill feed control lever contacts CC21-3 (Fig. 13a) are in series with the card feed control relay R11 so that when they are shifted by an energized CC21, relay R11 is allowed to pick up to start the card feed normally. Contacts CC21-3 also serve when in the normal unshifted position to provide a bill feed circuit to relay C4 which in turn makes the bill feed clutch magnet BF available to run out the two last bills when no bills issue out of the hopper. The CC21-2 contacts provide a circuit path to pick up relay C4 when bills are not issuing and the runout key is depressed. Contacts CC21-1 provide a holding circuit for relay CC21 along a path through line 320 (Fig. 13b), wire 334, cam contacts BF5, contacts CC21-1, the holding coil of relay CC21, wire 335 and line 321.

The bill feed card lever circuit through relay CC21 (Fig. 13b) is made to operate one cycle earlier than normal by shunting the bill lever contacts BLC with bill sensing relay contacts CC28-4 and a bill feed comparing switch.

Relay CC28 (Fig. 13d) is activated by an extra brush 282' at the bill sensing station when no bill is present at the station. The circuit includes line 320, bill feed switch BF1 on for comparing, cam contacts BF13, common brush 339, contact roll 281, brush 282', relay CC28, wire 340 and line 321. It is already noted that contacts CC28-4 of relay CC28 give an early indication of the absence of a bill form. The circuit for CC28 is held as noted in Fig. 13b by the circuit through line 320, wire 334, cam contacts BF6, relay contacts CC28-1, holding coil CC28, wire 335 and line 321. Other contacts CC28-2 and CC28-3 (Fig. 13d) are normally closed so that when bills are present they provide a circuit path to the bill feed circuit breakers BF11 and BF12 for sending sensing impulses to the bill sensing brushes 282. They also provide a circuit path through wire 341 and resistances RE1-RE20 to comparing storage relays CC1-CC20 for pre-energizing them to make them quicker to respond later when selectively energized by the bill perforations.

The bill feed hopper contact (Fig. 13a) opens the tabulator start interlock circuit to relay R12 when the bill feed hopper is empty. Other tabulator circuits are opened by contacts 342 when the tabulator card magazine is empty.

Relay CC23 (Fig. 13d) is a bill feed control relay which is picked up by closure of contacts 343 which are operated by the upper card lever of the card feed in the tabulator. Related contacts CC23-1 provide a circuit connection (Fig. 13a) for picking up feed control relay C4 on run-in conditions when the bill feed card lever relay CC21 is energized, to open lower contact CC21-3 but close lower contact CC21-2, and the lower card lever contacts C1-BL are closed. Other related contacts CC23-2 (Fig. 13a) open the circuit to the feed control relay R11 when the bill feed fails to feed on the run-in.

Relay C4 is picked up through the bill feed lever contacts CC21-3 when cam contacts CB31 close and allows the bill feed to run because of the C4AL closure even when bill forms are out of the hopper. The related contacts C4AU not only provide a holding circuit through cam con-

tacts CBC1 for the holding coil of relay C4, but they also provide a circuit for energizing the printer clutch control relay R16. Other contacts C4BU open the circuit of the running control relay R12 and stop the machine one cycle after bills run out. Still other contacts C4BL are shifted to operate the printer clutch magnet PCM when the bill feed runout circuit is operating.

A control is provided by relay C6 to prevent line spacing during ejection. One pickup coil C6-PL (Fig. 13a) is picked up through cam contacts CB-C4 and contacts C3-AL when relay C3 is energized for an ejection. Another pickup coil C6-PU is picked up with relay C4 when the bill feed is run without bills. A holding circuit for relay C6 (Fig. 13b) is established through line 320, wire 334, cam contacts BF6, contacts C6A, hold coil C6 and wire 335 to line 321. The normally closed contacts C6B in series with the line space magnet LSM are opened to prevent spacing during the ejection of a bill.

By means of the operation of the bill and card levers and the energization of the relays CC21 and C4, the presence of bills and cards is determined to govern the operation of the feeding devices for both and to control other parts of the machine depending on the presence of control record cards and print receiving bills. The machine stops when out of cards or bills under control of the C4 and CC21 relays. If relay CC21 is energized and relay C4 is deenergized, only the card feed will run. If relay C4 is energized and CC21 is deenergized, then only the bill feed will run. The operator can determine which feed is empty by merely depressing the start key. This causes only the feed which is empty to run. If the bills run out while controlling, the recording of a card group is completed on the last bill form before the machine stops. If the operator wishes to remove the remaining cards or bills, he may remove those from the magazine or hopper and then depress the start and run-out keys simultaneously to bring out the cards from the interior of the card feed and bill feed attachment mechanisms.

A number of bill feed switches are provided and when these are arranged in the off position, the tabulator can be provided with automatic paper carriages of the mechanical type or of the tape controlled variety.

Throughout this specification, reference is made to bill forms and it may be noted here that such forms are usually in the shape of record cards of the usual height, and a portion of each such form is perforated with account number indicia in the usual Hollerith code, i. e., columns of perforation positions are provided with 12 index points to a column and in which the duodecimal figures are represented by indicia designated 9, 8, 7, 6, 5, 4, 3, 2, 1, 0, 11, 12 starting from the bottom of the form. This is the same order in which the index points appear on the control record cards used in the tabulator. However, in the tabulator, the cards are fed with the bottom of the record as the leading edge and they go through the machine in the inverse order with the digit perforations appearing 9, 8, 7, etc. In the bill feed attachment, the bill forms are advanced with the top edge of the bill as the leading edge and therefore the index perforations are sensed in the order 12, 11, 0, 1, etc. But this difference is compensated for by the contacts of the bill sensing code relays which are so connected to a common digit emitter as to

give an inverted reading; for example, the "9" reading (which is the last code setting) is made the first to control an emitted digit comparing impulse.

Cooperating with the bill sensing brushes 282 (Fig. 13d) are a number of sets of account number code storage relays which are used to invert, store and compare the account number data appearing on the bill form with related account number perforations appearing in one or a group of related record cards. The parts of these storage and comparing relays are shown in Figs. 13d and 13e, the portion in the middle of Fig. 13d being the pickup portion of the relay storage unit. There it is seen that the relays are arranged in five sets, there being four related relays such as CC1-CC4 for one denomination and there being five such denominational arrangements. The four relays CC1-CC4 are representative of the digits 1, 2, 3, 6, respectively, and are picked up in combinations by appropriately timed BF cam contacts. At the bottom of Fig. 13d is shown the holding coils for all the storage relays and this portion acts as a secondary storage unit for holding one bill reading before a second bill reading is sent into the pickup coils. The third portion of the relay controls is shown in Fig. 13e where the contacts of the five sets of denominational storage relays are set up with labyrinth circuits to pick out one inverted impulse per column according to the bill perforations sensed and stored by the relays. A common emitter E is connected to all of the labyrinth circuits to send timed digital impulses into a comparing section of group control relays and these impulses are selectively derived according to the code closure settings of the contacts.

Referring back to Fig. 13d, it is seen that, by means of plug wire connections such as wire 336, any of the storage relay banks or columns may be connected to any of the bill sensing brushes 282. As shown, five columns of code relays are provided for detection of account number perforations.

The four storage relays of a denomination have a coded value to be representative of digits when called into action in a combination. For example, in the first column, relays CC1, CC2, CC3 and CC4, are representative of the digits 1, 2, 3 and 6 respectively. They are called into operation in combination for the larger digits. For example, for digit 5, the relays CC2 and CC3 are both called into action and, for the digit 9, both relays CC3 and CC4 are called into operation.

The following chart shows the representation of the various digits and the corresponding operation of combinations of code storage relays in the first and fifth columns:

Digit	Numerical Designation	Col. #1, Relay Energized	Col. #5, Relay Energized
1	1	CC1	CC17
2	2	CC2	CC18
3	3	CC3	CC19
4	3+1	CC3-1	CC19-17
5	3+2	CC3-2	CC19-18
6	6	CC4	CC20
7	6+1	CC4-1	CC20-17
8	6+2	CC4-2	CC20-18
9	6+3	CC4-3	CC20-19

At this point, sample circuits may be traced to show the picking up of a reading from the bill form, the storage of such a reading and a comparing circuit to compare the bill data with the supposedly related record card data. Assuming

that a digit perforation 9 appears in the first column of the account number field on a bill form, then the storage circuit pickup is as follows: Line 320 (Fig. 13d), switch BF1, wire 359, contacts CC28-2 and CC28-3, cam contacts BF-1 and BF-12, common brush 339, contact roller 281, bill sensing brushes 282, a plug wire 336, wire 361, rectifiers RC3 and RC4, relays CC3 and CC4, wires 371 and 372 to cam contacts BF16, BF17 and BF18, respectively, and wire 373 to line 321.

The foregoing pickup circuit is held during the next cycle by means of the following circuit: Line 320, switch BF1, wire 359, wires 375 and 376, cam contacts BF3, wire 374, relay contacts CC3-1 and CC4-1, holding coils CC3 and CC4 and line 321.

With relays CC3 and CC4 energized, reference to Fig. 13e shows that the corresponding contacts CC3-3 upper and CC4-3 upper are closed in series with the 9's sector of the emitter E so that during a comparing cycle, the comparing circuit is directed as follows: Line 320, circuit breakers CB1-4, relay contacts C5AL, cam contacts CF17 and CF18, wire 378, the emitter common segment 380, brush holder 379 revolved by a tabulator CF shaft in synchronism with the card feed, the "9" spot and wire 381, upper contacts CC3-3 and CC4-3, plug socket 338 and a wire to socket 372 (Fig. 13e), group control relay R164, closed contacts R175B and line 321. At the same time, related control relay R163 gets a comparing impulse from the card under the upper brushes UB (Fig. 13e) to socket 371. This plug wiring from an UB socket to 371 is part of a split plug connection, the other part going to socket 388 of the control section of the group control devices.

From the foregoing, it may be gathered that account number perforations of bill forms are compared with interspersed single or multiple card groups in the card feed unit. A comparison is made between the card in the bill feed unit and the first card of each group in the tabulator at the upper brushes. Then a comparison is made of the remainder of the same record card group by the usual automatic group control mechanism. It is noted that the group control mechanism is in effect divided into two sections, one for comparing cards for account number differences within a control card group and the other section for comparing the first card of a control group with the related bill form.

When there is a miscomparison or no-equal condition as evidenced by an emission from an unequal impulse from the section of the group control devices including relays R163 and R164 devoted to the card to bill comparison, then the machine is stopped and a signal light is illuminated to make the operator aware of the condition. Thus, the lack of equality in this section of the group control devices differs from the usual action of the other section of the group control devices which, upon sensing differences in card group designations, merely initiates total taking operation. When a no-equal stop circuit is set up, it is held until both bill feed and card feed have been emptied. Printing is suppressed during the runout operation which is caused by the operation of runout key. The no-equal circuit is carried to the comparing entry relay CC25 as follows: Line 320 (Fig. 13c), wire 383, cam contacts CB17 and CB18, one displaced and one normally positioned contact R163B and R164B,

23

socket 386, a plug wire to socket 357 (Fig. 13b), relay CC25, wire 335 and line 321. The other card control section of the group control devices (Fig. 13c) are plugged for bill feed control from socket 385 to socket 358 (Fig. 13b) to pick up the other control relay CC26 which has joint effect with relay CC25 as explained hereinafter.

At this point, it is well to summarize the effect of the comparing operation. It is noted that the impulses through the bill feed circuit breakers BF-1 and BF-12 cause the bill to be read under brushes 282 (Fig. 13d) and the reading to be set up in storage relays CC1-CC20. These storage relays are used to invert the account number reading and store it until the first card of a supposedly related control card group passes under the upper brushes UB in the tabulator. A labyrinth circuit (Fig. 13e) is set up by the contacts of the storage relays for each column of comparing data. Those labyrinth circuits are impelled on each card feed cycle by a common emitter E driven by a tabulator CF shaft. Thus timed impulses corresponding to the bill account number are emitted from the storage exit plug sockets such as socket 338. The storage relay exit sockets are plugged to a comparing set of group control relays and the related upper brushes UB are plugged to an opposed and matching set of group control comparing relays. Although a non-equal impulse may be emitted during consideration of a group of cards while running through the card feed, the only non-equal impulse accepted is that occurring along with the indication of a group change. In other words, recording on a preceding bill is not interrupted due to a non-equal comparison indication relating to a following bill, so that the machine stops only after finishing recording on the bill which has satisfied the comparing devices. The no-equal impulses coming from the two different sections of the group control devices are directed into the different control relays. The no-equal impulse from the comparing set of group control relays is plugged to the comparing entry socket 357 (Fig. 13b) and the no-equal impulse from the control field of the group control relays is plugged to socket 358 (also on Fig. 13b). An error control relay CC27 is picked up by the concurrent action of relays CC25 and CC26 which are operated from a group change impulse to a control entry socket and a non-equal impulse to the comparing entry socket.

A signal light SL is activated to indicate the error and the error relay CC27 will be maintained energized until the records have been run out of both the card feed and the bill feed.

The circuit to the card feed brushes is opened by contacts C5AL (Fig. 13e) so that no record will be printed in error during the runout period. However, if the machine is controlled for a total cycle when an error occurs, the total will be taken before the machine stops and before printing is suppressed.

Before explaining how non-equal comparison and group change impulses through the comparing and control relays CC25 and CC26 effect the operation of bill feed and the tabulator, it will be well to point out three ejection and feed control relays which are influenced by the conditions in the tabulator. These three relays are identified as relay C2, relay C3 and relay CC22 (see the middle of Fig. 13a).

Relay CC22 is seen to have a plug socket 351 and this is connected to receive a class of total impulse by plugging to a socket such as the MI

24

class of total socket 348 (Fig. 13e) or MI skip socket 349 (Fig. 13b). When relay CC22 is picked up, the corresponding contacts CC22-1 close in series with the holding coil through cam contacts CB27, wire 355, contacts CC22-1, relay CC22 and wire 312 to the line. A branch circuit is also established through the printer cam contacts PMC1 to pick up the other control relay C3.

Relay C3 is seen to have a pick up coil in series with a plug socket 352 which is available for other tabulator ejection control in addition to that established by CC22 and contacts PMC1 when ejecting from a total cycle as already explained. Socket 352 may be plugged to the digit selector DS (Fig. 13b) to be picked up by the sensing of any digit perforation in a selected card column or socket 352 may be plugged to a cycle control outlet normally provided in a tabulator for creating an impulse on each cycle and, in this instance, used as a single item ejection control.

Of the contacts controlled by relay C3, the contacts C3AL are in series with the holding coil C3 and establish a holding circuit through cam contacts PMC2 and PMC3. The other contacts C3B are seen to be in series with the bill feed clutch magnet BF and a circuit is established therethrough to operate the bill feed at either 6° or 186° by the circuit involving line 320, wires 319 and 321, contacts C3B, bill lever contacts C1AU, cam contacts CBC3, cam contacts BF1, wire 328, magnet BF and line 321.

The contacts C3B have a normally closed pair for providing a holding circuit for the relay C2. The holding circuit includes line 320, wires 319 and 321, contacts C3B, contacts C2AU, the holding coil of relay C2 and wire 312 to line 321.

Relay C2 is picked up from a number of sources by means of the two plug sockets 353 and 354 connected therewith. The one control for picking up relay C2 is through a X perforation in a card which is sensed by a card sensing brush and plugged to the socket 354, the impulse being timed by the closure of cam contacts CFC1 in series therewith. Other controls for relay C2 are effected through connection to socket 353. One of these connections involves control by a digit or unequal impulse through the socket 353. In other words, by plugging to the digit selector (Fig. 13b) any perforation in a selected card column is available for control over ejection and in a similar manner, connection to the plug socket such as socket 385 (Fig. 13c) is effective to convey an unequal impulse signifying a change in group to call for ejection control by relay C2. Other minor, intermediate and major total selection may be plugged to socket 353 (Fig. 13a) to call for classified total control of ejection by plugging from a socket such as the MI class socket 348 (Fig. 13e) or MI skip socket 349 (Fig. 13b) to socket 353 (Fig. 13a) and call in relay C2 to bring the bill feed operation into play.

It is already noted that the holding coil of relay C2 is held energized through the closure of related contacts C2AU (Fig. 13a) and the normally closed side of relay contacts C3B.

Relay C2 exercises control over two other pairs of contacts C2AL and C2B for governing bill feed operation. In Fig. 13a, it is seen that contacts C2AL are in series with the pickup coil of relay C4 and prevent it from being picked up with bills out until an ejection takes place.

The other contacts C2B, when closed, provide a circuit to energize the bill feed clutch magnet

BF through cam contacts CBC2 when the bill feed cycle is at 186°. The circuit includes line 320, wire 319, cam contacts CBC2, wire 365, contacts C2B, wire 366, cam contacts BF8, wire 328, clutch magnet BF and line 321.

It is noted hereinbefore that the comparing and control test relays CC25 and CC26 (Fig. 13b) are picked up by no-equal impulses through the contacts of the comparing and control relays R163 and R164, R129 and R130 (Fig. 13c) respectively. Both of these test relays have control over the error relay CC27 (Fig. 13b) and it in turn operates contacts to stop the machine and signal the operator when bills and cards do not agree.

Referring to Fig. 13b, it is noted that when comparing test relay CC25 is picked up, related contacts CC25-1 are closed and a holding circuit is directed as follows through the holding coil of relay CC25: Line 320 (Fig. 13d), the bill feed comparing switch BF1, wire 359 (Fig. 13b), cam contacts CBC6, relay contacts CC25-1, holding coil CC25 and wire 335 to line 321.

In a similar fashion, the holding circuit for relay CC26 is established through its contacts CC26-1.

Both test relays when effective together, close the normally open contacts CC25-2 and CC26-2 in series with the pickup coil of the error relay CC27. The error test circuit includes line 320 (Fig. 13d), switch BF1, wire 359 (Fig. 13b), wire 361, cam contacts CBC7, relay contacts CC25-2 and CC26-2, pickup coil CC27 and wire 335 to line 321. The related "stop" socket is available for other desired error controls.

A holding circuit for error relay CC27 is established through the lower card lever relay contacts of the tabulator as follows: Line 320 (Fig. 13a), wire 313, card lever contacts R3b, wire 362 (Fig. 13b), relay contacts CC27-1, holding coil CC27, wire 335 and line 321.

When the error relay CC27 is made effective by a lack of equal comparison, it exercises control in three positions to affect the operation of the machine. The related relay contacts CC27-2 (Fig. 13a) in series with the running control relay R12 of the tabulator are opened to stop the machine when an error occurs. Other relay contacts CC27-4 (Fig. 13b) are closed in series with the bill feed card lever relay contacts CC21-4 and provide a second holding circuit from the error relay CC27 and also provides a sustaining circuit for the signal light SL which is first picked up through wire 382. The circuit for this involves line 320 (Fig. 13d), switch BF1, wire 359, bill card lever relay contacts CC28-2 and CC28-3, wire 360 (Fig. 13b), relay contacts CC21-4 and CC27-4, the pickup coil CC27, and signal light SL in parallel therewith, and wire 335 to line 321. In this manner, the signal is maintained until the bills are cleared out of the bill feed unit. The third error control is exercised by the closure of contacts CC27-3 (Fig. 13e) to provide a test circuit for the pickup coil of relay C5 for preventing printing on the runout operation following an error.

The pickup circuit for relay C5 (Fig. 13e) is directed through line 320, circuit breakers CB1-4, cam contacts CB23, error relay contacts CC27-3, pickup coil C5, and wire 344 to line 321. A holding circuit is established for relay C5 (Fig. 13b) through contacts C5AU closed in parallel with the holding circuit for relay CC27 already mentioned as being held through wire 362 and the lower card lever tabulator contacts R3b (Fig. 13a).

Relay C5 exercises non-printing control by opening the contacts C5AL (Fig. 13e) to break the circuit through cam contacts CF17 and CF18 and the card analyzing brushes.

The rectifiers RC1-RC20 shown in Fig. 13d are of the type IN34 crystal diodes and are used to prevent back-circuits in the storage relays when the coding cams BF14-BF18 open and close the code circuits. They also prevent back-circuits to the bill sensing contact roll 281 when the pre-energizing circuit is established.

The resistors RE1-RE20 shown in Fig. 13d are wired in series with the pickup coils of the storage relays CC1-CC20 and also in series with the contacts CC28-2 and CC28-3 of the bill card lever control relays CC28 to permit pre-energization of the pickup coils to reduce the pickup time and at the same time avoid actuation of the coils because the resistors keep the current to a non-operative level.

When the operator notes the error signal and wishes to clear the machine of cards and bills, he depresses the start key (Fig. 13a) to close contacts ST along with depression of the runout key RK. This serves to pick up relays R11 and C4, the former being made effective by R12d and R11C to call the tabulator card feed clutch magnet CFCM into operation and the latter, through the shifting of the contacts C4AL, serves to operate the bill feed clutch magnet BF. The circuit for relay C4 includes line 320, wire 302, cam contacts CB31, relay contacts R61C, R68b, R12d, switch BF3, relay contacts CC21-3 lifted by the presence of bills, relay contacts C1BL, key RK, pickup coil C4, wires 303 and 304 to line 321.

The foregoing section of this specification deals mainly with the equal, no-equal control over the operation of the bill feed device by a comparison between bills and cards. By means of the showings, mainly in Figs. 4, 5, 6 and 13a to 13e, it was explained that upon a lack of comparison, the machine is stopped and a signal is given to the operator that there is need to rearrange either the bills or the cards.

Another modification of the bill feed control is the high, low, passing control which is about to be explained with reference to Figs. 7 to 12 and Figs. 14a to 14f. There are many points of similarity between the high, low control and the equal, no-equal control described hereinbefore. They are both coordinated with the same kind of tabulating and bill feeding mechanism and they both involve the use of code relays for inversion, storage and comparing. The main difference between the two systems of comparing control resides in the fact that with the high, low, passing control the operation is more automatic and continuous because when a miscomparison is sensed either the bill feed or the card feed is maintained in operation to endeavor automatically to bring about an equal comparison without attention on the part of the operator.

In order to avoid repetition of the description of controls applying in both instances, whenever the high, low control involves a tabulator or bill feed operation already described in connection with equal, no-equal control, then such a control is not explained hereinafter. It is the purpose in describing the high, low control to cover only those features necessary for an understanding of the different mode of operation so that the specification is confined to the essential differences which need to be pointed out for an understanding of the invention.

Figs. 7, 8 and 9 show in a diagrammatic way

the first three cycles of operation for high, low, passing control. The happenings in Fig. 7 are seen to be the same as those in the first cycle for equal, no-equal control. In the second cycle (Fig. 8), the first bill A passes through feed rollers 88 and 107 and the buckling position and the first card A passes through the upper brushes UB of the tabulator and its account number is read into the card feed storage side of the comparing unit. At about 165° in the cycle, the card feed storage readings are tested against the bill feed storage readings and it is assumed that an equal test results. Then the second bill B passes through the feed rollers 88, 89 and is read by brushes 282 for a second or pickup reading into the bill feed relay storage unit. At the same time, the second card B passes into the first tabulator feed rollers.

In the third cycle (Fig. 9) both feeding devices are run and the first bill A goes to the platen 112 and is printed upon and then moves into the feed rollers 123 and 124. Meanwhile, the second bill B passes through feed rollers 106, 107 to the buckling position. The third bill D (which is assumed to be out of order) passes through the feed rollers 88 and 89. Meanwhile the first card A passes the lower brushes LB for printing control and the second card B is read at the upper brushes UB for the card feed storage operation. At the same time, the third card C enters the first card feed rollers. A second testing is made of the card feed storage reading against the bill feed storage reading and it is assumed that it results in another equal test. Then the third bill D is read into the pickup side of the relay storage unit.

Figs. 10, 11 and 12 show in a diagrammatic way the fourth, fifth and sixth cycles of operation for high, low, passing control. In the fourth cycle, the first bill A is thrown into the stacker while the second bill B goes around the platen for printing reception. Meanwhile, the third bill D approaches the buckling position. The fourth bill E passes through the first bill feed rollers 88, 89 but remains short of being read by the comparing brushes 282. At the same time, the first card A is put into the tabulator stacker while the second card B is read at the lower brushes and the third card C is read at the upper brushes and the last mentioned reading is directed into the card feed storage side of the comparing unit. The fourth card D enters the first card feed rollers.

The account number reading of the third bill D in the feed bill storage unit is read against the account number of the third card C in the card feed storage unit and the result is found to be a high test showing that the account number of the third bill D is higher than the account number of the third card C. Because the test is high, the bill feed is latched at 186° and the fourth bill E is stopped short of being read by brushes 282. The reading of the third bill D stays in the storage unit and is only dropped out later when the bill feed operates again.

During the fifth cycle (Fig. 11), the bill feed stands idle due to the previous high test. Meanwhile, the third card C passes through the lower brushes LB at high speed on a tabulator cycle. The fourth card D passes through the upper brushes and it is read into the card feed storage unit while the fifth card F enters the feed rollers. At 165° the comparing device again functions to test the reading of the matching fourth card D against the reading of the third bill D and it is found to result in an equal test. At this point,

it becomes necessary to bring about a conversion of the testing result because when the machine is running at high speed the bill feed cannot be clutched in at 186°. Therefore the equal test is converted automatically into a low test because this condition sets up a slow speed cycle.

On the sixth cycle (Fig. 12), the card feed does not operate and a comparing test is made at 165° which results in an equal test. This is the same equal test as in the preceding cycle but in this sixth cycle it is proceeding at slow speed and the bill feed is actuated along therewith to bring the fourth bill E through the reading brushes 282 so that its account number is stored after the equal test is being taken. As a result, the bill feed mechanism starts to operate at 186° and then the second bill B moves away from the platen and the third bill D moves towards the platen in readiness to receive printing impressions under control of the matching fourth record card D at the lower brushes LB. The reading of the fourth bill E is transferred to hold and sets up corresponding contacts in the relay storage unit in readiness for the next testing cycle.

The operation of high, low, equal passing control is illustrated in connection with a billing application wherein each bill is presented for multiple listings of items followed by a total printed at a predetermined position on the bill. During the course of bill feeding operations, the bills are sensed by the bill feed sensing brushes 282 (Fig. 14e) causing the control information (account number perforations) thereon to be read into the five sets of comparing code storage relays CC1-CC20. As each detail or item card R passes the upper brushes UB in the tabulator card feed unit, the account number perforations therein are read and entered into corresponding sets of comparing code storage relays CP1-CP20 (Fig. 14d). (This differs from the equal, no-equal kind of comparison in that the group control relays R163, R164 (Fig. 13c) are not used. And the labyrinth circuits illustrated at the right in Fig. 14f are not used for the high, low control but are illustrated merely to show the universality of the code storage devices as being available for either equal, no-equal or high, low control.)

Simultaneous with the foregoing comparing operation, the normal group control in the tabulator is exercised between the record cards passing the upper and lower brushes in order that the grouping relationship of record cards can be determined. Upon a change in group control from one account number to another account number, a comparing circuit becomes active to permit an evaluation to be made of the bill and card account numbers set up in the code storage relays CC1-CC20 and CP1-CP20, the standing of the contacts thereof in Fig. 14c being representative of either a high, equal, or low comparison.

The significance of a high comparison reading is that the account number punched in the bill is larger in magnitude or higher in value than the account number punched in the detail card with which it is being compared. In other words, a bill is missing for the particular group of detail cards passing through the tabulator. Thereupon circuit means become operative to cause the tabulator card feed unit to bypass the unmatched and unwanted detail cards. The passing operation continues until an equal condition is reached in combination with a group control change

whereupon card feeding is disabled and a total taking cycle is initiated.

At the start of the total cycle, the minor first card impulse (MI 1st card, Fig. 13a) causes the bill at the platen to be advanced by skipping operation to a predetermined line for reception of total printing. Following the printing of the total, a bill feed ejection operation is initiated by a minor class of total impulse out of socket 348 (Fig. 14f) in order to eject the printed bill and to present the new bill for printing, said bill having indicated an equal condition. During the listing of each item on the bill, the spacing of the bill is under control of the line spacing magnet LSM of the tabulator. When passing controls are being exercised, the circuit to the line space magnet LSM is disabled to suppress spacing operations.

The occurrence of a low bill feed comparison reading attending a group change indicates the absence of related detail cards for that particular bill. Then the bill feed unit will be operated to feed and pass bills as long as the low comparison condition prevails. During the bill passing operation, the tabulator card feed unit remains inactive. Upon a change from the low reading to an equal bill feed comparison reading, the card feed unit resumes feeding operations and again the listing of items is resumed until the occurrence of another group change.

Before presenting a detailed explanation of the circuits concerning the comparing operations, it is well to consider the certain preliminary circuits dealing with the run-in control which cause the bill and card feeds to operate. The start key (Fig. 14a) of the tabulator is depressed to close contacts ST in order that relay R12 may be picked up. The closure of relay contacts R12BU (Fig. 14b) in series with the auto start relay R11 causes it to be energized to call into operation the card feed unit of the tabulator. A portion of the card feed control circuit involving relay contacts R11BL is shown at the lower right-hand corner of Fig. 14a and the control circuits therefore involving the pickup and holding coils of relay R11 are shown in the central upper section of Fig. 14b to be influenced by bill feeding control relays as explained hereinafter.

Operable along with the card feed clutch circuit, other circuits are completed to cause the tabulator printer clutch and the bill feed clutch to operate. With reference to Fig. 14a, this circuit is traceable as follows: Line 320, wire 394, normally open contacts C4AL, wire 395, cam contacts CB-C3 and BF-7 to a post before magnet BF from which one branch circuit can be traced through the bill feed clutch magnet BF, whereas another branch leads to the print clutch magnet PCM conditioned by a normal open C4BL contact. Both the C4AL and C4BL contacts are in their energized positions by virtue of a circuit traceable as follows: Line 321 (Fig. 14b), wire 397, pickup coil C4, normally closed skip control contacts C2AL, normally closed bill card lever contacts CC21-3, bill feed switch BF3 now "on," contacts R-12BU normally open now closed and then to the line 320 by means of total control contacts R68AU and R61B and cam contacts CB31.

Returning again to Fig. 14a, we find a hold circuit for relay C4 as follows: Line 320, wire 398, cam contacts CBC1, relay contacts CP28-3 normally closed, contacts C4AU, hold coil C4 and wire 399 to line 321. Relay C4 has other nor-

mally closed contacts C4BU in series with the tabulator running control relay R12.

Along with relay C4 holding coil, there is also wired in parallel a pickup coil of relay C6, the contacts C6B (Fig. 14b) of which is normally closed to enable the platen line space magnet LSM to be operative.

During the first card feed cycle, the detail card encounters an upper card lever contact 343 (Fig. 14e) which closes to energize a relay CC23. This card lever and contact have been added in the tabulator card feed near the first pair of feed rolls. In the bill feed, the first bill passes through the bill feed brush sensing station (Fig. 14e) thereby insulating a zero brush 282' from the contact roll 281. The presence of a bill card at the bill feed sensing station is therefore evidenced by the fact that relay CC28 is prevented from being picked up by a bill feed contact BF13. Relay CC28 is held through BF6 (Fig. 14b) and contacts CC28-1.

Directly thereunder it is seen that contacts CC28-4 remain closed in shunt with the bill feed comparing switch around the bill feed card lever contacts BFCL to energize the pickup coil of CC21 when a bill feed cam contact BF4 closes. Upon closure of contact CC21-1, a circuit is established through BF5 for the hold coil CC21.

By virtue of the first card feed and bill feed cycles, relays CC23, CC28 and CC21 are energized to enable a second feed cycle for both the card feed and bill feed.

For the second card feed cycle, the card feed control relay R-11 is energized as follows: Line 321, wire 397 (Fig. 14b), pickup coil R11, normally closed contacts CP25-3 and C02AL, wires 400, 401, bill feed switch BS4 "on," wires 402 and 403, normally open contacts CC21-3, bill feed switch BS3, relay contacts R12BU, R68AU, R61B, cam contacts CB31 and line 320.

The pickup for bill feed control relay C4 (Fig. 14b) for the second bill feed cycle is energized as follows: Line 321, wire 397, coil C4, normally open card lever relay contacts CC23-1, normally open bill feed card lever relay contacts CC21-2, normally closed lower card lever relay contacts C1BL, wires 402 and 403, normally open contacts CC21-3, bill feed switch BS3, relay contacts R12BU, R68AU, R61B, cam contacts CB31 and line 320.

During the second card feed cycle, two conditions develop, namely: (1) The closing of the lower card lever contacts LCLC (Fig. 14b) causes the energization of the relay C1 which in turn opens contacts C1BL and disables the pickup circuit to the bill feed control relay C4. (2) The occurrence of a first card group control change causing card feeding to be halted and also permitting the high, low, equal circuit to be effective. Upon the assumption that the first bill and first card contain equal control numbers, an equal reading will therefore result and cause a bill feed eject operation, thereby advancing the bill to its initial printing position.

In condition 1, the lower card lever contact LCLC and the relays controlled thereby are shown in the lower left part of Fig. 14b. There the usual card lever relays R-3 and R-4 are shown and also the added control relay C1. When said relay C1 is energized, not only is the C1BL contact opened to disable the pickup circuit to the bill feed control relay C4, but the contact C1AU (Fig. 14a) is closed to enable bill feed ejection, and contact C1AL (Fig. 14b) is opened to stop card feeding when the first card reaches the lower brushes,

and then card feeding is dependent on contacts CC21—3.

Before attempting an explanation of the operations presented in condition 2, it will be best to describe how the control information (account number) from both the bill and card is stored in the code storage relays. In storing the account number sensed by the bill feed, it will only be necessary to trace a circuit for one position of storage. Assuming that a digit "3" is to be read from the bill, the circuit is traceable as follows: Beginning with line 320 (Fig. 14e), switch BF1, wire 359, normally closed relay contacts CC28—2, bill feed circuit breakers B. F. 1 and B. F. 12, common brush 339, contact roll 281, bill feed sensing brush 282, plugwire 336 to storage entry socket 406, rectifier RC3, storage relay CC3, a common wire to bill feed cam contacts B. F. 16 and wire 407 to line 321. Upon the closure of contact CC3—1, an obvious hold circuit for CC3 is established and controlled by a bill feed cam contact B. F. 3. In the center of Fig. 14c, there is shown in the comparing labyrinth circuit a contact CC3—2 now transferred to its energized position.

Now returning to an explanation of the storing of the card control information sensed by the upper brushes UB, reference is made to the left of Fig. 14f and to the middle of Fig. 14d. The upper brushes UB (Fig. 14f) are connected by means of plugwire from socket 408 to the high, low, passing card storage entry socket 409 shown in Fig. 14d. The storing of a digit "3" in the first position of storage is traceable as follows: Beginning with an upper brush, the circuit continues by way of the plugwire (not shown) to entry hub 409, the pickup coil of storage relay CP3, rectifier P11, common wire 410, card feed cam contact CFCP3, and wire 411 to line 321. Upon closure of CP3—1 contacts (Fig. 14c), an obvious hold circuit is immediately established for the holding coil CP3 and controlled by card feed cam contacts CFCP5 and switch HLP. Again referring to the comparing labyrinth circuit at the bottom of Fig. 14c, there is shown an associated pair of contacts CP3—2 and CP3—3 contacts representing "3" in the units order and now transferred to their energized positions.

Now that the control information is stored, means for testing said control information will now be described. As mentioned in condition 2, a "first card" control change permits a testing of the information stored in the storage relays. The unequal impulse from a group control socket such as 385 (Fig. 13c), caused by the "first card" control change is plugged not only to the minor shunt hub (Fig. 14b), but also to the bill feed control entry hub 413 (top of Fig. 14d), as well and therefore causes the pickup coils of relays CC26 and CP23 to be energized. Relay CC26 is used in connection with the error feature as part of the error test preparations for CC27 as explained hereinbefore.

Upon closure of the contact CP23—1 (Fig. 14c), a holding circuit for relay CP23 is immediately established and controlled by cam contacts CFCP5. The closure of relay contacts CP23—4 renders the high, low, equal labyrinth circuit effective and, by virtue of the two "3" values stored therein by transfer of CC3—2, CP3—2 and CP3—3, an equal "exit" impulse will be emitted therefrom upon the closure of the cam contacts CBCP1. This equal exit impulse is traceable as follows: Beginning with line 320 (Fig. 14c), the circuit continues by way of the high, low, passing

control switch HLP now "on," cam contacts CBCP1, predetermined skip relay contacts CP30—2, contacts CP29—2 now closed but normally open to prevent testing on idle cycles, relay contacts CP23—4, and then through the labyrinth closures CC4—2, CP4—3, upper CC3—2, lower CP3—2, CC2—2, upper CP2—3, wire 414, etc. and eventually to the equal "exit" hub (bottom of Fig. 14c) by way of the remaining normally closed contacts in series therewith. In view of the fact that the equal "exit" hub is connected by means of a plugwire to the equal "entry" hub, and the "plug to B. F. eject" hub 415 is connected by means of a plugwire to the "D" eject hub 352 located in the lower left part of Fig. 14a, a bill feed ejection control will therefore follow, and the circuit may be traced as follows: Beginning with the equal "exit" hub in Fig. 14c, the circuit continues by means of a plugwire (not shown) to the equal "entry" hub, normally closed relay contacts CO5B, rectifier 416, normally closed relay contacts CP27—2, "plug to bill feed eject hub" 415, by a plugwire (not shown) to the D-eject hub 352, eject control relay C3 and wire 399 to the line 321. Upon closure of the C3B contacts (Fig. 14a) the bill feed clutch magnet BF will be energized to cause the advancement of the first bill to its initial print receiving position. The circuit is traceable as follows: Line 320, wire 394, normally open contacts C3B, lower card lever contacts C1AU, cam contacts CBC3 and BF1, bill feed clutch magnet BF and wire 418 to the line 321.

It is to be remembered that during the ensuing course of operations any subsequent occurrence of an equal impulse in combination with a group control change will not cause a bill feed operation by the circuit previously described. The reason being that the CP27—2 contact (Fig. 14c) will be open for these subsequent conditions. The reason for CP27—2 being open may be explained as follows: Referring back to the bottom of Fig. 14c, there is found in series with the equal "entry" hub, the pickup coil of a relay CP21 which will be energized upon the occurrence of an equal condition in combination with a control change. Upon the closure of CP21—1 contacts, a hold circuit is established for relay CP21 as controlled by the card feed cam contact CFCP5. The closure of contacts CP21—3 (Fig. 14d) permits the energization of relay CP27 through wires 419 and 420 (Fig. 14a) when the CB—31 cam contacts close during the following total taking cycle. Upon the closure of CP21—1 (Fig. 14d), a hold circuit for CP27 is established and controlled by the normally closed control contacts CO9AL in series therewith. CO9 relay (Fig. 14b) which is a total cycle control relay, is used instead of minor relay R63. CO9 also operates the print clutch on total cycles when the bill feed is low. Relay CP27 therefore remains energized until the occurrence of the next minor control change which occurs as the last item is being listed on the bill. The occurrence of the equal impulse at this time is inactive for the reasons previously stated.

After recording items, the advancement of the bill to a predetermined total line for the printing of a total is initiated by the minor first card control impulse out of socket 422 (Fig. 14b) which is plugged to the bill feed "D-skip" hub 353 (Fig. 14a). The predetermined total line skip circuit is traceable as follows: Beginning with the "minor first card" impulse, the circuit then continues by means of a plugwire (not shown) to the

D-skip hub 353 of the bill feed skip control relay C2, and through wire 399 to the line 321.

The closing of the C2AU contacts (Fig. 14a) establishes a hold circuit for relay C2 as follows: Line 320, wire 394, normally closed contacts C3B, contacts C2AU, the holding coil of relay C2 and wire 399 to line 321. Upon closure of the related C2B contacts, the bill feed clutch magnet BF is energized to cause skipping of the bill to a predetermined total line. The circuit is as follows: Line 320, wire 398, cam contacts CBC2, wire 422, normally open contacts C2B, cam contacts BF8, magnet BF and wire 418 to line 321.

During the total taking cycle (and following the printing of the total) a "minor class of total" impulse initiates a bill feed ejection operation to eject the first bill and bring up the second bill for initial printing. The ejection is caused by the following circuits: Beginning with the "minor class of total" impulse from socket 348 (Fig. 14f), the circuit continues by means of a plugwire (not shown) to the "total eject" hub 351, and through relay pickup coil CC22 and wire 399 to line 321. Upon the closure of related contacts CC22-1, an obvious hold circuit is immediately established for relay CC22 as controlled by cam contact CBC1. In series with contact CC22-1 is a printer cam contact PMCI which closes to energize the holding coil of the bill feed eject control relay C3. Upon closure of the related contacts C3AL, a hold circuit for relay C3 is immediately established and controlled by the PMC3 cam contacts. Upon closure of the normally open side of contact C3B, the bill feed clutch magnet BF is energized as follows: Line 320, wire 394, normally open contacts C3B, normally open contacts C1AU, cam contacts CBC3 and BF1, magnet BF and wire 418 to line 321.

One of the main objects of the device is to rapidly eject or pass along either the cards or the bills according to the kind of a miscomparison. In the operation of the passing controls two conditions will be considered namely: (1) the occurrence of a high impulse in combination with a group control change and (2) the occurrence of a low impulse in combination with a group control change.

In Fig. 14c, assuming a bill number "6" instead of "3" and then a high circuit is set up by the lifting of CC4-2 and a high circuit through wire 423 to the high "exit" hub and an impulse for condition (1).

In condition (1), the high impulse indicates the absence of a bill for the particular detail cards being sensed, therefore circuit controls will be exercised to cause the card feed to pass these detail cards until an "equal" card is presented. The controls to be exercised during high bill passing are as follows: (a) suspension of group control; (b) suppression of bill feed clutch and print clutch circuits; (c) suppression of alphabet print zoning; (d) suppression of accumulator control; and (e) suppression of the line spacing circuit.

Under a, the suspension of group control by a high impulse is accomplished by plugging the high "exit" hub to the opposite entry hub and thus picking up relay CP24 through relay contacts CP22-2. Thus, upon the occurrence of high impulse during a group change, relay CP24 is energized. A hold circuit for the holding coil of relay CP24 is established when the contacts CP24-1 close in series with cam contacts CB29.

A normally closed contact CP24-5 (Fig. 14b) is therefore caused to open and disable the pickup circuit to the group control relays minor

R61, etc., intermediate relay R67 and major relay R73. The suppression of group control relays permits the normal pickup circuit to the card feed control relay R11 (Fig. 14b) to be exercised, thereby permitting uninterrupted operations of the card feed until the occurrence of an equal condition.

Under b the suppression of bill feeding and printer clutch operations is caused by the fact that the circuit for the print clutch control relay R-16 is disabled by the opening up of a normally closed contact CO4BL (upper left of Fig. 14b). Referring again to the right side of Fig. 14a, it is seen that the print clutch magnet circuit is inoperative for listing operations when contacts R16A are in a de-energized position.

The energization of relay CO4 is caused in the following manner: Referring again to Fig. 14c, it is remembered that upon the occurrence of a high impulse during a control change, relay CP24 is caused to be energized.

Upon the closure of related contacts CP24-2 (Fig. 14d), the relay RCO4 is picked up and energized by cam contact CB-31 (Fig. 14b) in series therewith through wire 420. A hold circuit for relay CO4H is immediately established when contacts CO4AU close (Fig. 14d) and the circuit remains energized until the following card feed cycle when the controlling card feed cam contacts CF15 in series therewith, open up to disable the circuit. Another relay CO5 is seen to be called into operation with the holding coil of CO4.

Under c, the suppression of alphabet zoning is caused by the fact that the zone control magnet is likewise controlled by the CO4BL contact (Fig. 14b) previously mentioned as being used for disabling the R-16 relay circuit.

Under d accumulator control is suppressed by another CO4 contact (not shown).

Under e line spacing is suppressed by the opening of a normally closed CO5B contact (Fig. 14b) wired in series with the platen feed magnet LSM. It is already noted with reference to Fig. 14d that relay CO5 is energized along with the holding coil of relay CO4, the pickup of which was previously explained.

In condition 2, the occurrence of a low impulse in combination with a group control change signifies the absence of detail cards for the particular bill sensed, therefore circuit controls will be exercised to cause the bypassing of unrelated bills until a bill is presented which matches the detail card. The controls to be exercised during a low impulse are as follows: (a) The suppression of card feeding operations and (b) means for providing a circuit to the tabulator printer clutch in order that bill feed motive power may be secured for bill feed passing.

An example of a low comparing impulse may be given with reference to Fig. 14c and assuming the bill account number to be "2" instead of "3." Then the contacts CC2-2 are opened to break the "equal" condition circuit. But card comparing contacts CP3-3 are lowered (assuming a card number of "3" as before) and circuit connections are established to wire 425 which leads to the low "exit" hub which is pluggable to call relay CO2 into action. Relay CO2 is held through its contacts CO2AU (Fig. 14a) and cam contacts PMCP1.

Under a, the suppression of card feeding operations is accomplished by the opening of the contacts CO2AL (Fig. 14b) thereby disabling the card feed control relay R-11, the contacts R11BL (Fig. 14a) of which maintain energization of the card feed clutch magnet CFCM.

Under b, the means for providing a circuit to the printer clutch magnet PCM is shown in Fig. 14a where the circuit is traceable as follows: Beginning with the print clutch magnets PCM the circuit then continues through the normally open contacts CO2B now closed, wire 426, normally open relay contacts CO1B, cam contacts CB21 and the line. Energization of the printer clutch operates the tabulator drive and provides the motive power for the bill feed. Energization of the bill feed clutch magnet BF is later controlled by the bill feed circuits for total cycle operation as previously described.

Relay CO1 is energized along with the usual tabulator control relay R12 at the lower left corner of Fig. 14a.

When passing controls are being exercised, the group control exercised by the card feed is suspended. A circuit is provided to retain the initial group change detected at the start of passing operations and upon a completion of the passing operation said initial suspended control change becomes effective.

As previously explained, group control is suspended by virtue of the plugging (Fig. 14c) between the high "exit" and the opposite hub to carry an impulse to pick up relay CP24. Upon the occurrence of the unequal impulse during the first passing cycle, the minor shunt relay R-53 (Fig. 14b) is picked up and dropped out later in the same cycle. In order to retain relay R-53 in an energized state until the passing operation is complete, the following circuit is employed: Beginning with the minor shunt relay R-53 (Fig. 14b), the circuit continues through normally open contacts R53A and from this point, the retaining circuit follows through a normally closed minor high test control contact CP24-3 and wire 427 to the high, low, passing switch HLP and to the line 320.

In the event that a bill feed ejection is to be initiated as a result of a control change occurring during a high speed passing operation, a circuit is provided to delay the ejection until the following (idle) cycle in order to eliminate a close time condition. The close timing condition concerns the timing of the unequal test impulse resulting from a comparison between a "one" and a "zero." Since the occurrence of this impulse is so close to the clutching time of the bill feed, it is advisable to delay the bill feed operation until the following idle cycle. The circuits involved are shown mainly at the top of Fig. 14d.

When the printer is operating at high speed, normally open contacts CP26-2 wired in series with the "control entry" hub 413, are shifted to an energized position by virtue of action of a CP26 relay (bottom of Fig. 14a) being energized during high speed tabulator operations. Then upon the occurrence of an unequal impulse resulting from a "one" and "zero" test, the pickup coil of a relay CP25 is caused to be energized as follows: Beginning with the unequal impulse out of a group control device socket such as socket 385 (Fig. 13c), the circuit continues by means of a plug wire to the control entry hub 413 (Fig. 14d), the normally open contacts CP26-2, cam contacts CFP7, normally closed relay contacts CP23-3, pickup coil of relay CP25 and wire 419 to line 321.

Upon the closure of related contacts CP25-1 (Fig. 14c) a holding circuit for relay CP25 is immediately established and controlled by cam contacts CB29. Closure of CP25-2 contacts, in

series with cam contacts CB19, permit energization of an auxiliary control relay CO3. This relay CO3 is held energized by the closure of related contacts CO3AL in series with cam contacts CBCP3 and the hold coil.

The closure of related relay contacts CO3AU (upper left to Fig. 14c) renders the labyrinth circuit effective for the following cycle to cause an ejection.

- 10 Referring back to the top of Fig. 14d, the occurrence of an unequal impulse resulting from a "9" to "1" comparison as distinguished from a "1" to "0" comparison (during high speed cycle) causes the labyrinth circuit to be effective in the same cycle in the following manner. The unequal impulse causes energization of a relay CP23 as follows: Beginning with the control entry hub 413, the circuit then continues through the normally open contacts CP26-2 now closed by high speed operation, cam contacts CFCP6, pickup coil CP23 and wire 419 to line 321. A hold circuit for relay CP23 (Fig. 14c) is established through contacts CP23-1, cam contacts CFCP5 and switch HLP. And upon closure of contacts CP23-4, the labyrinth circuit becomes effective to cause an ejection just as though either an equal or a low comparison had taken place.

Run completing circuits are provided in order to insure completion of comparing operations for either the last card or the last bill before final "clearing out" operations are initiated. Two comparing conditions arise or may possibly exist when any one feed magazine becomes exhausted before the other, namely: (1) the occurrence of a high reading as the last bill leaves the bill feed magazine and (2) the occurrence of a low bill reading as the last detail card leaves the feed magazine. Upon the occurrence of either one of these two conditions, the printer stops.

- 40 In order to resume operations, the start key is depressed, whereupon either the card feed or the bill feed operates, depending upon the results of the previous comparison, until a change in bill feed comparison is occasioned after which the tabulator or the bill feed may be cleared of cards or bills. In explaining the run completing circuits for condition 1, reference is made to the middle of Fig. 14a where a relay CO6 is normally energized by a circuit including line 320, wire 429, the bill feed hopper switch BFH, bill feed hopper contact 430 closed as long as bills are in hopper, relay CO6, wires 431 and 399 to line 321. It is obvious that relay CO6 becomes de-energized when the bill feed hopper contact 430 opens up as a result of the last bill leaving the bill feed magazine. Accordingly a related contact CO6A opens to de-energize the start relay R-12 whereupon card feeding operations come to a halt.

When the start key is depressed, a circuit is completed through contacts ST, contacts CO6B and the pickup coil of a relay CO7, thereby causing a related contact CO7B to close to further permit a hold circuit to be established for start relay R-12 which was picked up in the normal manner. A hold circuit for relay CO7 (bottom of Fig. 14b) is immediately established upon closure of contacts CO7A in series with lower card lever relay contacts R3AU and it is held until the last card passes through the card feed.

70 In explaining condition 2 reference is made to the left of Fig. 14b where it can be seen that upon the opening of the card feed hopper contact 342, the hopper stop relay R49 is thereby de-energized causing the related contacts R49A (Fig. 14a) to

open and de-energize start relay R-12 which results in a halt to card feeding operations.

A contact R49B (Fig. 14a) also closes to cause the energization of a relay CO8 when the start key is depressed. Contacts CO8B are arranged in shunt (Fig. 14b) around hopper contact 342. The start relay R-12 is energized in the normal manner.

A hold circuit for relay CO8 is established when a related contact CO8A (Fig. 14b) closes 10 and is held by bill feed card lever relay contacts CC21-4 until the last bill passes through the bill feed.

When operating with the high, low, passing control, and during run-in conditions, there is provided means for an early disablement of the clutch control circuit so as to permit the comparing circuit to be effective immediately upon the test of the first test or comparison. This is done by the contacts CP28-3 (top of Fig. 14a) 15 which are called in by a high, low control relay CP28 and transfer the bill feed clutch circuit from control by cam contacts CBC1 to control by contacts CBC2 which break a half cycle earlier. Thus the reading of the first bill is not lost because the feed is shortened and the second bill is stopped short and prevented from being read into storage regardless of the outcome of the first comparison.

The aforementioned relay CP28 (Fig. 14d) is 30 called into operation early in high, low control operation by a circuit including line 320 (Fig. 14b), cam contacts CB31, wire 420 (Figs. 14b, 14c and 14b), high, low, pass switch HLP2, lower card lever relay contacts C1BU closed until cards are at lower brushes, upper card lever relay contacts CC23-3, bill feed card lever relay contacts CC21-6, relay CP28 and line 321.

Adjacent to relay CP28 (Fig. 14b) is a relay CP22 which is used for improving runout conditions under high, low, passing control of the bill feed. Relay CP22 is also energized through the high, low, passing switch HLP2, and contacts C1BU of the lower card lever relay, said contacts being closed as soon as cards are at the lower brushes, a descending switch, and contacts CC21-5 of the bill feed lever relay which is 45 energized as the last bill is ready for a runout.

Relay contacts CP22-3 (bottom of Fig. 14c) are so arranged in the comparing circuit that they cause a low bill feed reading to be interpreted as a high reading during the cycle in which the last bill is at the printing station, i. e., the low circuit instead of going through relay CO2 and over to the bill feed eject socket 415, goes over wire 433 and merely through relay CP24. The resulting artificial high reading causes operation of the card feed to feed the remaining cards until the card hopper is emptied.

Relay CP22 has other contacts CP22-2 (bottom of Fig. 14c) which are used to control bill runout operations whenever the bills and cards are arranged in a descending order. In uses of that kind the bill feed comparing controls are plugged in a manner opposite to that employed for ascending operations. Then the high "exit" hub is plugged to the low entry hub and the low "exit" is plugged to the high entry. On a runout of bills the comparing circuit will provide an impulse at the low "exit" and this low impulse must then be interpreted as a high impulse in order to call in the card feed for operation. The high control relay CP24 will be called in under runout conditions due to the fact that relay CP22 is made inoperative by the setting 60

"off" of the descending switch for descending sequence operation.

The comparing test circuit is ordinarily at 162° through contacts CBCP1 (top of Fig. 14c). But on an operation to skip to a predetermined total line, an alternative test circuit through contacts CP30-2 and cam contacts CBCP2 at 356° is closed in addition to the 162° test time. Relay CP30 (Fig. 14a) is picked up by a skip to predetermined line impulse either to socket 353 or 354. The 356° test impulse becomes operative on predetermined total cycles before the bill feed operates to cancel the status of the storage unit. In this manner an equal reading is provided so that both the bill feed and tabulator clutches are operated at the same time and the bill is spaced to the predetermined total line upon which the total is to be printed.

A contact CO5B (Fig. 14c) is used for properly 20 coordinating the bill feed and card feed in operations following a high bill feed reading, the tabulator being set for straight listing with no predetermined lines for totals. Without this contact the circuit is inadequate in that printing on bills is at wrong positions. The need for the contacts stems from the fact that in the cycle in which the high bill feed reading is detected, the bill feed clutch latches up at the mid-point of its cycle, while the tabulator latches up at the end of its cycle. In the operations that follow, the card feed is active to pass unwanted cards until an equal condition is detected. The occurrence of the equal condition caused the operation of both the tabulator and bill feed to be one half cycle out of step, thereby resulting in item printing on 25 incorrect lines of the bill.

It is noted hereinbefore that relay CO5 (Fig. 14d) is energized along with relay CO4 which is 30 called into operation by contacts CP24-2 of the high test relay CP24 (see bottom of Fig. 14c).

Returning to consideration of the function of contacts CO5B (Fig. 14c) in the comparing circuit, it is noted that they are connected to direct the equal impulse normally to relay CP21 and the bill feed eject socket 415, and when transferred to send the equal impulse to the low control relay CO2 and socket 415. During a high bill feed reading the contact CO5B is shifted, by means already noted, thereby diverting the ensuing equal impulse to relay CO2 generally employed for low bill feed operations. The energization of relay CO2 causes, as noted hereinbefore, the operation of the bill feed alone, thereby causing the bill to advance into print receiving position, and in the same cycle, a reading of a new bill is put into the storage unit. The result of the comparison that follows is a high bill feed reading, thereby causing the tabulator to start operations with the bill already placed in the print receiving position. Thus, through contacts CO5B, the required coordination of bill and card feed is obtained by virtue of the extra bill feed cycle gained through changing an equal test after a high test into a low test.

While there have been shown and described and pointed out the fundamental novel features of the invention as applied to two preferred embodiments, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a device for comparing the digital indicia on a pair of records for equality, means for sensing the indicia on one of the records, a set of four code relays representing digit values of 6, 3, 2 and 1, means under control of said sensing means for energizing said relays in combination, contacts operated by said relays, nine labyrinth circuits involving said contacts and made effective according to the digit sensed, an impulse emitter connected to said circuits, a pair of comparing relays, a second record sensing means operated in synchronism with said emitter and connected to one of said comparing relays, connections from the other of said comparing relays to said emitter, and means under control of said comparing relays for indicating equal or no-equal relations between the indicia of the pair of records.

2. A device of the kind set forth in claim 1 further characterized by the fact that each of said code relays includes pickup and holding coils for picking up an inverted reading of indicia on one record and storing said inverted reading to condition one of said comparing relays.

3. In a machine of the class described, means for analyzing the index point positions of a column of a record bill, a set of code relays representative of the digits 6, 3, 2 and 1, means under control of said analyzing means to cause a setting of contacts of said relays in combination in a circuit portion to represent the value of the perforation analyzed, means for analyzing the index point positions of a column of a control card, a comparing means with a circuit jointly completed by said contact means and said card analyzing means upon disagreement between the setting of said contact means and the location of the perforation in said card, manipulatively controlled means for running all cards and bills out of the machine, and means brought into operation by said completed circuit for stopping the machine and preparing it for control by said manipulatively controlled card and bill runout means.

4. In a record control machine for printing bills, said bills having classification indicia, and said records having classification indicia, means for feeding said bills in succession, means for feeding said records in succession, means for analyzing the indicia on said bills, means for analyzing the indicia on said records, two sets of code storage relays, one set controlled by said bill analyzing means and energized thereby in combination to be representative of the bill classification indicia, and the other set controlled by said record analyzing means and energized thereby in combination to be representative of the record classification indicia, high, low and equal labyrinth circuits for determining the magnitude of the bill classification indicia with respect to the record classification indicia, said circuits including contacts of both said sets of relays, means for line spacing the bills, means under control of the equal circuit for suspending operation of the bill feeding means while spacing and recording on a bill from a related group of records, means under control of the high circuit for suspending operation of the bill feeding means while controlling said record feeding means to operate until the equal circuit is completed, and means under control of the low circuit for suspending operation of the record feeding means while controlling said bill feeding

means to operate until the equal circuit is completed.

5. A machine of the kind set forth in claim 4 wherein each set of code storage relays includes a plurality of denominational groups of relays, each denominational group including four relays representative of the digit values 6, 3, 2 and 1, and energized in combination to represent the classification indicia, said labyrinth circuits comprising three main parallel lines wherein the contacts by sets are arranged in an ascending denominational order but within the sets in a descending digital order with single central bill indicia relay contacts arranged and connected alternately to double outer record relay contacts.

6. In a machine of the class described, means for successively analyzing the cards of a plurality of groups of cards, each card having indicia representative of a group number and a billing classification number, means for analyzing a succession of bills each of which has distinctive bill classification indicia, group control devices operated when card group numbers change, two sets of code storage relays, one set controlled by the card analyzing means and selectively energized according to the card classification number indicia, and the other set controlled by the bill analyzing means and selectively energized according to the bill classification number indicia, high, low and equal labyrinth circuits for determining the relative magnitude of bill and card classification indicia, said circuits being set up selectively by contacts of both sets of relays, means under control of said group control devices for testing the condition of said circuits whenever card groups change, and feeding and recording means under control of the one of the three circuits found effective by test for either passing out unmatched cards, passing out unmatched bills, or recording on a bill under control of a related group of cards.

7. A machine of the kind set forth in claim 6 with means for detecting when the equal circuit is effective along with an operation of the group change devices after card feeding induced by a "high" test, means under control of said detecting means for stopping the card feeding means, means for suppressing said group control devices until an equal circuit is effective, devices brought into operation by said group control devices to be effective before and after a total taking operation, a platen, means under control of the before total device for operating the bill feeding means to shift the bill to a predetermined total impression receiving position on the platen, and means under control of the after total device for operating the bill feeding means to eject the recorded bill and bring in a new bill and initiate operation of the card feeding means.

8. In a device for comparing the digital indicia on a pair of records for equality, means for sensing the indicia on one of the records, a set of four code relays representing digit values of 6, 3, 2 and 1, means under control of said sensing means for energizing said relays in combination, contacts operated by said relays, nine labyrinth circuits involving said contacts and made effective according to the digit sensed, an impulse emitter connected to said circuits, a pair of comparing relays, a second record sensing means operated in synchronism with said emitter and connected to one of said comparing relays, connections from the other of said comparing relays to said emitter, means under control of said comparing relays for indicating equal or no-equal

relations between the indicia of the pair of records, each of said code relays including pickup and holding coils for picking up an inverted reading of indicia on one record and storing said inverted reading to condition one of said comparing relays, resistances in series with the code relays and parallel with the sensing means therefore, and means for pre-energizing said relays through said resistances before the sensing means energizes them in combination, whereby a quick selective effect of code relay energization from the record analysis is effected.

9. In a device for comparing the digital indicia on a pair of records for equality, means for sensing the indicia on one of the records, a set of four code relays representing digit values of 6, 3, 2 and 1, means under control of said sensing means for energizing said relays in combination, contacts operated by said relays, nine labyrinth circuits involving said contacts and made effective according to the digit sensed, an impulse emitter connected to said circuits, a pair of comparing relays, a second record sensing means operated in synchronism with said emitter and connected to one of said comparing relays, connections from the other of said comparing relays to said emitter, means under control of said comparing relays for indicating equal or no-equal relations between the indicia of the pair of records, each of said code relays including pickup and holding coils for picking up an inverted reading of indicia on one record and storing said inverted reading to condition one of said comparing relays, resistances in series with the code relays and parallel with the sensing means therefore, means for pre-energizing said relays through said resistances before the sensing means energizes them in combination, means for detecting when no record is being sensed by the first mentioned sensing means, and means under control of said detecting means for calling said pre-energizing means into operation before a record is sensed.

10. In a record controlled machine for printing on a sequence of bills under control of related groups of records, means for sensing indicia on successive records, means for sensing indicia on a bill, a dual sectioned group control device, one of said sections being operated under control of said record sensing means to detect changes in record groups, and the other of said sections being operated under control of both sensing means to detect inequality between a bill and supposedly related records of a group, an error control means, means for calling said error control means into operation under control of both sections of said group control device only when inequality between bill and record is accompanied by a change in record groups, means under control of said error control means for giving an error indication and stopping the machine, printing devices under control of said record sensing means, means for suppressing said printing devices, means under control of said error control means for operating said suppressing means in preparation for a runout operation upon detection of inequality, means for feeding out unwanted records, a runout key, and means under control of said runout key for feeding out unmatched bills and stopping said record feeding means after the last bill is fed out.

11. In a record controlled machine for printing on a sequence of bills under control of related groups of records, means for sensing indicia on successive records, means for sensing indicia

on a bill, a dual sectioned group control device, one of said sections being operated under control of said record sensing means to detect changes in record groups, and the other of said sections being operated under control of both sensing means to detect inequality between a bill and supposedly related records of a group, an error control means, means for calling said error control means into operation under control of both sections of said group control device only when inequality between bill and record is accompanied by a change in record groups, means under control of said error control means for giving an error indication and stopping the machine, printing devices under control of said record sensing means, means for suppressing said printing devices, means under control of said error control means for operating said suppressing means in preparation for a runout operation upon detection of inequality, means for feeding out unwanted records, a runout key, and means under control of said runout key for feeding out unmatched bills and stopping said record feeding means after the last bill is fed out, means for determining the completion of item printing on a bill, and means under control of said determining means for preventing operation of said runout feeding means for preventing issuance of a bill until all related items are recorded thereon.

12. In a record control machine for printing bills, said bills having classification indicia, and said records having classification indicia, means for feeding said bills in succession, means for feeding said records in succession, means for analyzing the indicia on said bills, means for analyzing the indicia on said records, two sets of code storage relays, one set controlled by said bill analyzing means and energized thereby in combination to be representative of the bill classification indicia, and the other set controlled by said record analyzing means and energized thereby in combination to be representative of the record classification indicia, high, low and equal labyrinth circuits for determining the magnitude of the bill classification indicia with respect to the record classification indicia, said circuits including contacts of both said sets of relays, means for line spacing the bills, means under control of the equal circuit for suspending operation of the bill feeding means while spacing and recording on a bill from a related group of records, means under control of the high circuit for suspending operation of the bill feeding means while controlling said record feeding means to operate until the equal circuit is completed, means under control of the low circuit for suspending operation of the record feeding means while controlling said bill feeding means to operate until the equal circuit is completed, each set of code storage relays including a plurality of denominational groups of relays, each denominational group including four relays representative of the digit values 6, 3, 2 and 1, and energized in combination to represent the classification indicia, said labyrinth circuits comprising three main parallel lines wherein the contacts by sets are arranged in an ascending denominational order but within the sets in a descending digital order with single central bill indicia relay contacts arranged and connected alternately to double outer record relay contacts, manipulative means for changing the high circuit to control as a low circuit and vice versa for a change from ascending to descending order control, automatic means for changing the high

circuit to control as a low circuit and vice versa, and automatic means for changing an equal circuit to control as a low circuit, whereby record feeding is suspended momentarily to bring the bill feed into step therewith.

13. In a machine of the class described, means for successively analyzing the cards of a plurality of groups of cards, each card having indicia representative of a group number and a billing classification number, means for analyzing a succession of bills each of which has distinctive bill classification indicia, group control devices operated when card group numbers change, two sets of code storage relays, one set controlled by the card analyzing means and selectively energized according to the card classification number indicia, and the other set controlled by the bill analyzing means and selectively energized according to the bill classification number indicia, high, low and equal labyrinth circuits for determining the relative magnitude of bill and card classification indicia, said circuits being set up selectively by contacts of both sets of relays, means under control of said group control devices for testing the condition of said circuits whenever card groups change, feeding and recording means under control of the one of the three circuits found effective by test for either passing out unmatched cards, passing out unmatched bills, or recording on a bill under control of a related group of cards, means for detecting when the equal circuit is effective along with an operation of the group change devices after card feeding induced by a "high" test, means under control of said detecting means for stopping the card feeding means, means for suppressing said group
